UNITED STATES PATENT OFFICE.

FRANK R. McBERTY, OF EVANSTON, ILLINOIS, ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

Application filed November 12, 1903. Serial No. 180,858.

To all whom it may concern:

Be it known that I, FRANK R. McBERTY, citizen of the United States, residing at Evanston, in the county of Cook and State of Illinois, have invented a certain new and useful Improvement in Automatic Telephone-Exchange Systems, of which the following is a full, clear, concise, and exact description.

10 My invention relates to switching apparatus and circuits for use more particularly in telephone exchange systems, and its object is in general to provide improved means for switching lines for the purpose of communication, and for performing various selecting, signaling and other operations incident thereto. By employing the full equipment herein described it is possible to dispense with the services of a central office operator and provide for complete control of the automatic switching apparatus by the subscribers, but the invention is not limited in its application to a "full automatic" system, as many of the features described may advantageously be adapted independently of the others in different types of systems.

Another object of my invention is to provide improved and novel means, whereby a calling line may be served by any one of a plurality of connecting circuits, each adapted to interconnect such line with a line called, the selection of such connecting circuit by the calling line being accomplished by apparatus operating automatically and initially controlled by the calling line.

Another object of my invention is to provide new and improved means, whereby a plurality of lines terminating in the exchange may be normally associated for calling with an idle one of a plurality of connecting circuits, each adapted to connect the calling line to a called line and apparatus operated upon the taking for use by one of such lines of the connecting circuit with which the plurality of lines is normally associated, for transferring the remainder of such lines into operative relation with another idle connecting circuit.

50 Another object of my invention is to provide new and improved circuits and electromagnetic controlling apparatus, whereby the operation of the selector through which a

connecting circuit is connected to a called line may be accurately controlled and the 55 operation of such selector accomplished in a speedy and efficient manner.

Another object of my invention is to provide novel and efficient means, whereby a test may be made of a called line, and if upon 60 such test the line should be found busy, a busy signal will be thereupon automatically transmitted to the calling party.

A further object of my invention is to provide new and improved means whereby upon 65 the testing of the desired line, if such line is found to be in idle condition, a source of ringing current will be automatically applied to the terminal of such line for ringing the called party; and my invention further 70 provides that the reapplication of such ringing current may be under the control of the calling subscriber.

More particularly, my invention relates to a switching system involving improved organizations and arrangements of circuits and apparatus for facilitating the interconnection of telephone lines and the various features of my invention are shown more particularly in this application with reference to a full automatic telephone exchange system, in which the entire operation of the system for the interconnection of subscribers' lines is under the control of the calling subscriber. It must not be understood, however, that my invention, nor any of the several features thereof, are confined or restricted to the particular form shown herein, nor to the particular character of system indicated by the form shown herein, but may 90 be used wherever applicable or of advantage.

In accordance with one feature of my invention I provide in an exchange system a plurality of connecting circuits for the lines together with automatic transfer mechanism whereby an idle one of said connecting circuits is maintained in operative relation to the lines and automatic Y switches or line finders, preferably one for each connecting circuit, adapted when suitable controlling apparatus associated with the lines is actuated, as when a subscriber is calling, to extend the circuit of his line to a connecting circuit. By this arrangement the connecting circuits and therefore the line finders 100 may be less in number than the lines which 105

they serve. The controlling apparatus for the lines may be located at the substation and may comprise switches or keys actuated when a subscriber initiates a call. The transfer mechanism preferably comprises relays, one for each line finder, said relays being arranged so that when any line finder seizes a line calling, a relay is energized to shift the controlling circuit from the motor mechanism of that line finder to the motor mechanism of another idle finder in the series. The line finders themselves may be rotary switches having points of contact or stationary terminals for the lines and traveling brushes or contact members forming movable terminals of the connecting circuits. The lines are connected in multiple to the terminals of the several line finders associated with a given group of lines and in multiple also to the terminals of selectors for making connection with the wanted lines. In actuating the controlling apparatus when calling, the subscriber causes the electrical condition of his line at the terminals or stopping points of a group of finders to be changed and at the same time causes the motor mechanism of the particular idle line then in association with the group to drive its brush over the terminals of the lines in succession. When the brush reaches the terminal of the line calling, a circuit is closed for a stop magnet or other mechanism so that the brushes remain at that point in position to extend the line circuit, and at the same time the electrical condition of the line is restored to normal or otherwise changed again so that other line finders will not make connection with that line while it is busy. Preferably the line finders have no particular normal position, but after they have served one calling line they remain in that position until again energized.

In accordance with another feature of my invention a selector switch provided for making connection with the wanted line has testing means placed in operative condition when the switch has advanced to the terminals of such line and then actuated if the line is idle to energize a circuit including an electromagnetic device which in turn connects the ringing generator in circuit with the wanted line.

In accordance with another feature of my invention I provide in association with each selector switch a pair of devices which cooperate with the controlling apparatus to govern a double movement of the selector, preferably in long and short steps, together with transfer mechanism for shifting the operative relation of the calling mechanism from one of said devices to the other. These devices are preferably interrupters intermittently operated in the movement of the selector. As shown they are toothed or notched wheels, the distance between the

teeth or notches in the two wheels determining the length of the long and short steps respectively.

In the preferred form of my invention, the form illustrated herein, each telephone line extends from a substation to a plurality of connection terminals located in the central office, such terminals being referred to as "incoming terminals," where they appear in the automatic finder apparatus associated with said connecting circuits by which a calling line is united with a connecting circuit and as "outgoing terminals" where they appear in the automatic selector switches associated with said connecting circuits, by which said connecting circuits are adapted to be connected to a called line. The finder apparatus referred to involves structurally a contact arm carrying a plurality of contacts adapted to move such contacts over such incoming terminals, and to cause them to make contact therewith. Similarly the selector switches each comprise a contact arm adapted to sweep over such outgoing terminals and upon the selection of the desired line to cause such contact devices to make contact with the outgoing terminals of such line.

The preferred form of my invention, therefore, involves, briefly, telephone lines and a plurality of connecting circuits extending between finder devices and selector switches, each such connecting circuit having individual thereto and associated therewith one of such finder devices and selector switches and being connected to contact devices upon their respective contact arms. The substation comprising a part of each telephone line may be and is preferably provided with the ordinary and usual substation equipment and is further provided with switching or sender apparatus adapted when operated to control the connection of one or both of the limbs of the line to ground by means of which apparatus the subscriber may control the interconnection of his line with some other line of the exchange through one of said connecting circuits and the finder apparatus and automatic selector switch associated therewith.

My invention is illustrated with particular reference to the accompanying drawings, which illustrate an embodiment thereof, in which—

Fig. 5 is a rear elevation of the apparatus shown in Fig. 3;

Figs. 6 and 7 constitute, when taken together, a complete diagrammatic showing of one form of my invention and illustrate two telephone lines extending from substations to an exchange, a connecting circuit for uniting such lines and a finder and selector associated with such connecting circuit adapted to unite with such telephone lines, respectively, as such lines may be calling or called lines, the system as shown involving the circuits and organizations of the preferred form of my invention.

The same letters of reference designate the same parts in each of the figures of the drawings.

Referring first to the structure of the finder device and the automatic selector switch, Figs. 1 to 5, inclusive, show the preferred form of the automatic selector switch used in connection with my invention, the finder device being of similar construction as regards the terminal mounting and the movable contact arm, and differs but little except in the arrangement of circuits and electromagnetic operating mechanism from the selector switch.

The terminal mounting C of the finder or selector is mounted upon a suitable support C¹ and has mounted thereon a plurality of sets of connection terminals, one set of terminals for each line entering the exchange. These sets of terminals may each comprise four terminals; two of which serve as the terminals of the telephone lines with which they are associated, while the other two terminals form parts of local circuits associated with such line in the exchange.

Mounted centrally of the terminal support C is an electromagnet G through which passes longitudinally a shaft E mounted to rotate on suitable bearings, and having the arm D rigidly secured thereto upon the same side of the terminal support C that the terminals appear. This arm D is provided with an inwardly projecting portion D¹ to which is pivoted a contact carrying arm F, which encircles the shaft E immediately adjacent the electromagnet G, and is adapted to form the armature of such magnet. Upon the contact arm F at the end remote from the pivot thereof are mounted four collars H of insulating material, in which are slidably mounted the several contact devices or brushes I, I¹, I², I³. About these contact devices are placed helical springs, such springs being positioned between the heads of the contact devices and the collars of insulating material in such a manner that they tend to force the heads of the contact devices away from the insulating collars and in the direction of the connection terminals and the terminal support C. One or more of said springs and its associated contact device,

which is arranged to be maintained in contact at all times with one of the co-operating connection terminals, serves to maintain the contact arm F retracted from the electromagnet G and certain other of the contact devices notably the contact devices adapted to make contact with the line terminals, out of normal contact with their co-operating terminals upon the terminal support C. When, however, as will be readily seen, the electromagnet G is energized in any position of the contact arm F the arm will be drawn up close against the electromagnet and all four of the contact devices I, I¹, I², I³, will be forced into engagement with the co-operating connection terminals to which they are at that time adjacent; the magnet G at the same time locking the contact arm F in the position which it then occupies.

Rigidly fixed to the shaft E is a gear-wheel K, which gearwheel meshes with a train of power driven gears forming a part of the clockwork escapement mechanism adapted to drive the gearwheel K and through it the contact arm F. The operation of the clockwork mechanism, however, is normally prevented by a stop arm or clutch L controlled by the electromagnet M. This stop arm L engages the clockwork mechanism while the electromagnet M is in its normal and deenergized condition, and it will therefore be seen that when the magnet M is energized the clockwork mechanism will drive the shaft E and move the contact arm F until such time as the electromagnet M is again deenergized. This particular form of motor mechanism, while it is well adapted to the purpose in hand, it must be understood, is only typical and my invention is not restricted to this particular form. It may involve, in substitution therefor, any other form of motor mechanism adapted to perform the same function.

Upon the end of the shaft E adjacent to the contact arm F are mounted four insulated metallic rings N, N¹, N², N³, which are electrically connected with the contact devices I, I¹, I², I³, carried by the arm F. Contact springs O, O¹, O², O³, are mounted upon an insulating block P suitably secured to the support C¹, and are arranged to bear upon the said rings, these springs serving as terminals for the connecting circuit and local circuits as will be hereinafter described.

The apparatus thus far described is common to both the finder device and the automatic selector switch in the form of my invention shown herein. This apparatus, however, when used as a selector switch has in addition associated therewith three contact-making wheels R, T and S rigidly secured to the shaft E at the rear of the apparatus, which contact-making wheels are severally adapted to control the circuit of the release-magnet M. The contact-making

wheel R, which serves as an off-normal switch, is provided with but a single depression in its periphery in which, in the normal position of the selector switch, the contact spring R¹ rests. When, however, the selector switch moves from its normal position the contact spring R¹ rides upon the periphery of the wheel R and comes in contact with the contact R². These contacts R¹ and R² will then be held closed until such time as the selector switch is again in its normal position, when the contact spring R¹ will again enter the depression and circuit will be broken between such contact spring and contact R².

The contact-making wheel S operates similarly to close a circuit at the contact spring S¹ and the contact S², but the depressions in the periphery of the wheel S are of such extent and are so spaced that the contact spring S¹ will only be in contact with the contact S² while the selector contact arm is moving from co-operative relation with one set of connection terminals into cooperative relation with the next set of terminals. The contact-making wheel T also operates similarly to cause the contact spring T¹ to make contact with the contact T², but the depressions in the wheel T are of such extent in this case and are so located that while the contact wheel T is passing from one depression to the next, the selector contact arm will be moving over ten sets of connection terminals. It will be obvious of course, that in a selector in which the sets of connection terminals are arranged according to some other system than the decimal system of notation that the relation of the distance moved by the selector while the contacts S¹ and T¹ are moved from one depression to the next upon their respective contact making wheels may be changed as may be required.

The particular arrangement of the circuits and apparatus involved in the form of my invention shown herein will be considered in connection with the description of the operation of the system shown, and reference is now made, therefore, to Figs. 6 and 7 which, taken together, illustrate the particular connections and disposition of apparatus in this system. Two telephone lines are shown including the usual substation apparatus and are generally indicated as A and B respectively. The line A for purposes of illustration will be considered as the calling line, and it is assumed that connection is desired by the subscriber A with the line B.

At each substation in addition to the ordinary telephonic apparatus there is located additional switching or sender apparatus comprising the switches b and b¹, the switch b being adapted upon its depression to connect the limb 1 of the telephone line to ground, and the switch b¹ being adapted

upon its depression to connect the limb 2 of the line to ground. These switches b and b¹ may be of any desired character, but are adapted to be independently or simultaneously closed and opened as may be found necessary.

The first act of the subscriber A to bring about the establishment of the connection desired is to depress and thereby close both of the switches b and b¹, thereby grounding both limbs of the telephone line. The closure of the switch b establishes a circuit from the battery e, magnet M, conductor 3, back contact and armature of the relay v, back contact d² and armature d¹ of the relay d, limb 1 of the telephone line and switch b to ground and back to battery. The closure of this circuit serves to operate the magnet M of the first connecting circuit, assumed in this instance to be idle, which magnet attracts the stop arm L allowing the clock-work mechanism to advance the contact arm F over the successive sets of incoming connection terminals indicated in Fig. 6 as a¹, a², a³, a⁴. The connection terminals a¹, a² as will be seen form the permanent terminals of the telephone line, being connected to the limbs 1 and 2 respectively. The terminal a³ is connected by the conductor 4 and the back contact d⁴ and the armature d³ of the relay d to limb 2 of the telephone line. The connection terminal a⁴ is connected by the conductor 5 to the relay d and thence to ground. These connections a¹, a², a³, a⁴ may be multiplied as may be desired and do, in fact, appear in each of the finder devices, one of which finder devices is associated with each of the connecting circuits of the exchange, there being as many connecting circuits as may be necessary to properly carry the traffic of the exchange. As is indicated at the top of Fig. 6 the limbs 1 and 2 of the telephone line may be also multiplied to outgoing connection terminals appearing in each of the selector switches, whereby the telephone line A may be reached by some other line when such other line is calling, the lowermost terminal of the line finder F being connected to the lowermost terminal of the line connector indicated above it, whereby the cut-off relay d and the busy test relay W may be simultaneously operated upon connection being made to a line by either a line finder or line connector.

The particular function and arrangement of these multiple terminals of the selector switch will be hereinafter described and referred to in the description of the connection with the telephone line B and need not here be further considered.

It will at this point be noted that while my invention involves the use of a plurality of connecting circuits with their associated apparatus, but one of such connect-

ing circuits is shown in full; sufficient of the associated circuits and apparatus of a second connecting circuit being shown, however, to make clear the manner in which connection will be made with a second connecting circuit in case the first connecting circuit is in use as will be hereinafter set forth.

The contact arm F in its movement causes the contact device I², which is the contact device adapted to normally make contact with its cooperating connection terminal, to trail over and make contact successively with the connection terminals a³ of the respective lines. When the contact arm F reaches the connection terminals of the line, the switching apparatus of which has been operated as above described, a circuit will be closed by the contact device I² and the connection terminal a³ from the battery e², relay l, conductor 9, contact device I², connection terminal a³, armature d³ and back contact d⁴ of the relay d, limb 2 of the telephone line, switch b¹ to ground and back to battery. Relay l is thereupon energized and attracts its armature which completes a circuit from the battery e through the relay m, magnet G, conductor 10, front contact and armature of the relay l to ground and back to battery. The closure of this circuit energizes the relay m thereby closing a circuit from the battery e to the relay v by way of the conductor 42, and also energizes the magnet G, which draws down and locks the contact arm F with the contact devices I, I¹, I², I³ in contact respectively with the connection terminals a¹, a², a³, a⁴. The closure of the circuit through the relay v causes it to attract its armature opening at the rear contact thereof, the normal connection to battery of the limbs 1 of all of the telephone lines through the magnet M of the finder device associated with the first connecting circuit and closing at the front contact thereof a substitute connection to battery for such lines through the conductor 43 and the magnet M of the finder device associated with the next or a subsequent one of said connecting circuits. By this means, immediately upon the taking for use of the first connecting circuit, all the lines, with the exception of the first calling line, which have been to this time normally associated with the first connecting circuit are transferred from association with such connecting circuit into association with a second connecting circuit, and the limb 1 of each of such transferred lines will be, until the first connecting circuit is again idle, connected with the magnet m of the second connecting circuit, and upon the calling of a second line the magnet M of the second connecting circuit will be operated similarly to the operation above described of the magnet M of the first con-

necting circuit. Such second calling line will be, therefore, automatically connected to the second connecting circuit by an operation of the finder apparatus associated therewith similar to that above described with relation to the first connecting circuit.

Upon the drawing down of the contact arm F a circuit is established from the battery e¹ through conductor 6 and relay f, whence it divides into two paths, the one through the relay g, conductor 7, back contact and armature i¹ of the relay i, relay j, contact device I, connection terminal a¹, limb 1 of the telephone line, switch b to ground and back to battery; and the other through relay k, conductor 8, back contact and armature i² of the relay i, relay n, contact device I¹, connection terminal a², the limb 2 of the telephone line, switch b¹ to ground and back to battery.

The energization of the relay f by the closure of the circuit described attracts its armature and momentarily closes a circuit from the battery e through relay m, magnet G, conductors 10 and 11, armature and front contact of the relay f, conductor 12, conductor 13, conductor 16, armature and back contact of the relay r, conductor 17, back contact p³ and armature p⁴ of the relay p, armature and back contact of the relay o, conductors 17 and 14, magnet M¹ to ground and back to battery. The establishment of this circuit energizes the magnet M¹, but almost immediately upon the establishment of this circuit, the energization of the relay g establishes a circuit from the battery e through the conductors 10, 11, 12, 13, back contact and armature q¹ of the relay g, conductor 40, armature and front contact of the relay g, conductor 15, relay r, (which may be made slightly sluggish in its attractive movement) to ground and back to battery. This energizes the relay r which opens the original energizing circuit of the magnet M¹. The magnet M¹, however, having been momentarily energized by this original circuit, has withdrawn the stop-arm L¹ from stop relation to the clock-work mechanism driving the selector arm F¹. The initial movement of the arm F¹ and the shaft E upon which it is mounted has also moved the wheels R, S and T from their normal position and has closed the contacts R¹ and R², S¹ and S², and T¹ and T². The closure of the contacts S¹, S² at this time is ineffective, owing to the retracted position of the armature p¹ of the relay p. The closure of the contacts R¹, R² is for the purpose of returning the selector to normal after conversation has ceased or in case of any abnormal operation of the finder arm F, or the apparatus associated therewith, resulting in the deenergization of the relay m. With a circuit established through the contacts R¹, R² it will be obvious that if at any time the magnet m should

be deenergized a circuit will be established from the battery e through the armature and back contact of the relay m , conductor 39, contacts R^2 and R^1 , conductor 14, magnet M^1 to ground and back to battery. This circuit will be maintained until the wheel R is again in its normal position and the selector arm in its normal position at which time the contact spring R^1 on entering the depression 10 in the periphery of the wheel R will open the circuit and bring the selector to a stop. In the ordinary operation of the system it is necessary, at this time, that is upon the momentary closure of the original operating 15 circuit to the magnet M^1 , to consider only the contacts T^1 and T^2 , which, immediately upon the first movement of the selector, have closed a circuit for the magnet M^1 in substitution for the original circuit, such circuit 20 being from the battery e through conductors 10, 11, 12, 13, relay o , armature p^1 and back contact p^2 of the relay p , contact T^1 , contact T^2 , conductor 14, magnet M^1 to ground and back to battery. This circuit will be 25 maintained until the contact spring T^1 again enters the depression in the periphery of the wheel T , during which time the selector will have passed over the connection terminals of ten lines and will have been brought from its 30 normal or false zero position into its true zero position and is now ready for selection. At the same time the relay o energized by the closure of this circuit has, by the attraction of its armature, maintained the original 35 energizing circuit of the magnet M^1 open allowing it to close again only upon the opening of the contacts T^1 , T^2 at which time it is open at the relay r .

A further result of the drawing down of 40 the arm F by the energization of the magnet G and the energization of the relay f has been the closure of the circuit from battery e through conductors 10, 11, armature and front contact of the relay f , conductor 12, contact I^3 , connection terminal a^4 , relay d to ground and back to battery. The closure of this circuit has energized the relay d which thereupon opens the circuits of the 45 conductors 3 and 4, at its armatures d^1 , d^3 , respectively, the opening of the circuit of the conductor 4 resulting in the deenergization of the relay l , which opens the original energizing circuit of the magnet G and the relay m , but since the various circuits closed 50 by the operation of the armature of the relay f also include the magnet G and the relay m they will both remain in energized condition. The opening of the conductor 3 by the relay d results in the prevention of 55 the energization of the magnet M of the finder apparatus associated with the second connecting circuit by the ground placed upon the limb 1 of the line A as previously indicated and hereinafter referred to which 60 would otherwise occur.

The apparatus associated with the first connecting circuit and now associated with the calling line A is at this time in readiness for selective operation by the subscriber at the substation of the line A . For the purpose of illustration it will be assumed that the number of the line B , with which connection is desired, is 57. It will, therefore, be necessary for the subscriber A to step the selector arm F^1 forward to the 57th line 70 from the true zero position of the arm F^1 of the selector. This will be accomplished by first stepping the arm F^1 forward five long steps from the true zero position under the control of the contact wheel T and its 75 associated contacts, in each step passing over the connection terminals of ten lines. This being accomplished it will cause the contact arm F^1 to take seven short steps under the control of the contact wheel S and its 80 associated contacts S^1 and S^2 , each step passing from connection terminals of one line to the connection terminals of the next. This being accomplished it will cause the contact arm F^1 to take seven short steps under the control of the contact wheel S and its 85 associated contacts S^1 and S^2 , each step passing from connection terminals of one line to the connection terminals of the next. To accomplish this selection it is only necessary for the subscriber A to properly manipulate 90 the switches b and b^1 . His first act is to five times successively open and close the switch b . The first opening of the circuit through the switch b has caused the deenergization of the relay g , which in turn by the 95 retraction of its armature has caused the opening of the circuit hereinbefore described to the relay r . The deenergization of the relay r has closed a circuit from the battery e through conductors 10, 11, 12, 13 and 16, 100 armature and back contact of the relay r , conductor 17, back contact p^3 and armature p^4 of relay p , armature and back contact of the relay o , conductors 17 and 14, magnet M^1 to ground and back to battery. The 105 energization of the magnet M^1 by this circuit has again started the movement of the contact arm F^1 and the movement of the wheel T with the contact arm F^1 immediately closes the circuit through the contacts T^1 , T^2 , hereinbefore described to maintain the magnet M^1 energized until the contact spring T^1 again rests in the depression upon the 110 periphery of the wheel T , in which time the selector arm F^1 has passed over the connection terminals of ten lines, the relay o in the meanwhile maintaining the original energizing circuit of the magnet M^1 open. In the meanwhile also the subscriber has 115 again closed the switch b energizing the relay g over the same circuit as before, which in turn again energizes the relay r as before described. The contact arm F^1 will, therefore, again come to a stop until a further opening of the switch b . Each subsequent 120 opening and closure of the switch b during tens selections will similarly step forward the selector arm F^1 and bring it to a stop after the connection terminals of ten lines have 125 been traversed. The subscriber A will, 130

therefore, have opened and again closed the switch b five times in the particular selection assumed and the contact arm F^1 now rests over the connection terminals of the line No. 50.

The next act of the calling subscriber A will be to maintain the switch b closed and open the switch b^1 . The opening of the circuit hereinbefore described through the switch b^1 deenergizes the relay k , which in turn by such deenergization closes a circuit from the battery e through conductors 10, 11, 12 and 18, armature and back contact of the relay k , conductor 19, relay q , relay p to ground and back to battery. The closure of this circuit through the relay q energizes this relay, which draws up its armatures and closes for itself a locking circuit from battery e through the conductors 10, 11, 12, 13 and 23, armature q^2 and front contact q^3 of the relay q , conductor 44, relay q , conductor 19, relay p to ground and back to battery. This locking circuit will thereupon maintain relays q and p energized, subject only to the control of the relay f , which in turn will be maintained energized until the energization of the relays s and i .

The retraction of the armature of the relay k by the opening of the switch b^1 has opened the circuit to the relay t heretofore established by the energization of the relays f and k from the battery e , conductors 10, 11, 12, 18 and 20, relay t to ground and back to battery. The opening of this circuit deenergizes the relay t which permits the retraction of its armature and closes a circuit from the battery e through conductors 10, 11, 12, 13 and 21, armature and back contact of the relay t , conductor 22, front contact p^5 and armature p^4 of the relay p , which is now energized, armature and back contact of the relay o , conductor 17, conductor 14, magnet M^1 to ground and back to battery. The energization of the magnet M^1 again allows the selector arm to move forwardly, moving therewith the wheels S and T. This movement of the wheels S and T again causes the closure of the contacts T^1 and T^2 and S^1 and S^2 , but since the relay p is now energized and the contact p^2 is no longer in contact with the armature p^1 the closure of the contacts T^1 , T^2 , is no longer effective and attention need only be given to the closure of the contacts S^1 and S^2 . The closure of these contacts has established a circuit from the battery e through conductors 10, 11, 12, 13, relay o , armature p^1 and front contact p^6 of relay p , conductor 24, contacts S^1 and S^2 , conductor 14, magnet M^1 to ground and back to battery. This circuit will be maintained until the contact spring S^1 rests in the next succeeding depression in the periphery of the wheel S, during which movement of the wheel S the contact arm F^1 is moved from over the connection terminals

of the line 50 to adjacent the connection terminals of the line 51. Meanwhile the subscriber A has again closed the switch b^1 which has again energized the relay k through the circuit heretofore described, which in turn has again energized the relay t through the circuit heretofore described, which in drawing up its armature has opened the circuit to the magnet M^1 through the conductor 22 and the front contact p^5 and the armature p^4 above described.

The subscriber A then continues to open and close the switch b^1 until he has done so seven times in all, each opening of the circuit causing the selector arm F^1 to take one short step under the control of the contact-making wheel S and thereby bringing it adjacent the connection terminals b^2 , b^3 , b^4 , b^5 of the desired line No. 57, each such short step being accomplished similarly to the first such short step as above described.

The subscriber A having now fully accomplished selection his next act is to maintain the switch b^1 closed and open the switch b . The opening of the circuit hereinbefore described through the switch b again causes deenergization of the relay g , which allows its armature to retract and thereby closes a circuit from the battery e through the conductors 10 and 35, armature and front contact of relay n , which is now closed due to the closure of the switch b^1 , conductor 40, relay s , relay i , back contact and armature of the relay g , conductor 40, armature q^1 and front contact q^4 of relay q primary winding h^2 of the induction coil h , conductor 31, contact device U^2 of the selector arm F^1 , connection terminal b^4 associated with the line B, conductor 33, armature and back contact of the relay W , which is deenergized if the line desired is idle, to ground and back to battery. Upon the closure of this circuit, which, as will be noted, will only occur if the guard-relay W is deenergized, the relays s and i will be energized and attract their armatures. The drawing up of the armature i^6 of the relay i closes a locking circuit for such relay from the battery e through conductors 10 and 35, armature and front contact of the relay n , relay s , relay i , armature i^6 and front contact i^5 of the relay i , conductor 37, magnet G^1 of the selector switch, contact device U^3 upon the contact arm F^1 , connection terminal b^5 , conductor 34, magnet W to ground and back to battery. This circuit not only provides a locking circuit for the relay i , but also serves to energize the magnet G^1 and the guard-relay W . The relay W thereupon draws up its armature and removes the normal ground connection from the conductor 33 and the connection terminal b^4 and substitutes therefor a busyback X connected to said conductor 33 and terminal b^4 by the condenser Y .

and conductor 45 for purposes hereinafter to be described.

At the same time simultaneously with the energization of the relay W, the magnet G¹ has been energized, drawn down the arm F¹ and locked it in position with the four terminals U, U¹, U², U³, each in contact with its respective cooperating connection terminals b², b³, b⁴, b⁵ of the desired line B.

It will at this point be noted that in the selector switch the contact devices U² and U³ make contact at all times with the connection terminals b⁴ and b⁵, respectively, of the set of terminals over which the contact arm F¹ rests and in the movement of the arm trail over the several connection terminals b² and b³, serving in this manner not only to complete the test circuit and holding circuit through such terminals when selection is completed, but also to hold the arm F¹ in its normally retracted position.

The energization of the relay i has also attracted its armatures i¹ and i², breaking the circuit heretofore maintained through the relays k, g and f but immediately connecting the limbs of the telephone line to the conductors 29 and 30 by the respective front contacts i³, i⁴. A circuit is thereupon established from battery e³, conductor 30, front contact i⁴ and armature i² of the relay i, relay n, contact device I¹, connection terminal a², limb 2 of the telephone line A, switch b¹ to ground and back to battery. This circuit will maintain the relay n energized, although the original energizing circuit for this relay has been broken.

The energization of the relay s by both the original energizing circuit and the locking circuit of the relay i has, as will be noted, established an alternative energizing circuit for the relay d from the battery e, conductor 10, conductor 38, armature and front contact of the relay s, conductor 36, contact device I³, connection terminal a⁴, relay d to ground and back to battery, which circuit, since it has been established before the deenergization of the relay f, will prevent at this time any release of the relay d.

Immediately upon the energization of the magnet G¹ which has resulted in the connection of the limbs 1 and 2 of the telephone line B to the contact devices U and U¹ of the switch arm F¹ through the connection terminals b² and b³ a ringing current will pass over the telephone line B from the source of ringing current V, back contact and armature u¹ of the relay u, conductor 25, contact device U, connection terminal b², limb 1 of the telephone line B, the condenser and ringer at the substation of such line, limb 2 of the telephone line, connection terminal b³, contact device U¹, conductor 26, armature u² and back contact thereof of the relay u back to the source of current. This current will ring the bell

of the called substation and such circuit will be maintained until the relay u is energized by a further act of the calling subscriber.

The next act of the subscriber A by which the connection of his line to the line desired is completed is to remove his receiver from its hook, listen for the busy signal and then open switch b¹. This completes a circuit from the battery e³, conductor 30, front contact i⁴ and armature i² of the relay i, relay n, contact device I¹ upon the finder arm F, connection terminal a², limb 2 of the telephone line A, the transmitter and receiver at the substation of such line, limb 1 of the telephone line, connection terminal a¹, contact device I upon the finder arm F, relay j, armature i¹ and front contact i³ of the relay i, conductor 29 and back to battery. This circuit in addition to energizing the relay n, which has already been maintained energized over a portion of this circuit, energizes the relay j and causes it to attract its armature. This closes a circuit from the battery e⁴, relay u, conductor 32, front contact and armature of the relay j to ground and back to battery. The closure of this circuit energizes the relay u which attracts its armature, cutting off the source of ringing current from the conductors 25 and 26 and connecting the conductors 27 and 28 to the conductors 25 and 26, respectively, thereby completing the transmission circuit from the substation A to the substation B, such circuit including the respective windings of the induction coil indicated adjacent the common battery e³ as is usual.

All that is now required to accomplish conversation between the two substations is the removal of the receiver at the substation B from its hook, which establishes a metallic circuit from the battery e³, conductor 28, front contact and armature u² of the relay u, conductor 26, contact device U¹ upon the selector arm F¹, connection terminal b³, limb 2 of the telephone line B, the transmitter and receiver at the substation of such line, limb 1 of the telephone line, connection terminal b², contact device U upon the selector arm F¹, conductor 25, armature u¹ and front contact thereof of the relay u, conductor 27 and back to battery. By this circuit the substation B is supplied with talking battery from the central station according to standard common battery practice. Similarly the substation A is also supplied with talking battery over the metallic circuit hereinbefore described which circuit includes the relay n and the relay j, the battery supply to this station being also according to standard common battery practice.

If the subscriber B should fail to respond promptly, the subscriber A may again signal the subscriber B by closing one of the switches b or b'. This places a ground upon

the telephone line thereby shunting the relay *j* which allows its armature to retract, opening the energizing circuit of the relay *u*. The deenergization of the relay *u* permits its armatures *u'* and *u''* to retract and the ringing circuit hereinbefore described is again established. After a suitable period the subscriber A will again cut off the ringing current and reestablish the transmission circuit complete by opening the switch *b* or *b'* which has been closed again energizing in a manner heretofore described the relays *j* and *n*.

As soon as conversation is completed the 15 subscribers replace their receivers upon their hooks. The hanging up of the receiver at the substation B does not in any way affect the apparatus by which the circuit is completed and should the subscriber B for any reason hang up his receiver before the 20 conversation is completed the subscriber A may again signal him in a manner that has been heretofore described, the entire connection being wholly under the control of the subscriber A at the calling station. When, 25 however, the subscriber at the calling station A replaces his receiver upon the hook the relays *j* and *n* are both deenergized. The armature of the relay *n* in falling back breaks the energizing circuits of the relays *m*, *s*, *i* and *W* and of the magnets *G* and *G'*; furthermore, the deenergization of the relay *s* has opened the energizing circuit of the relay *d*, causing it to retract its armatures, 30 the relay *f* having been deenergized upon the initial energization of the relay *i* and now being maintained deenergized on account of the opening of the various circuits at the calling substation.

The deenergization of the relay *d* has again restored the line connections of the telephone line A to normal, thereby completing again the local circuits through the conductors 3 and 4.

The deenergization of the magnets *G* and *G'* has allowed the respective arms *F* and *F'* to retract and the connection of the contact devices *I*, *I'* and *I''* with the connection terminals *a'*, *a''* and *a'''* respectively and the contact devices *U* and *U'* with the connection terminals *b''* and *b'''*, respectively, is broken.

The finder device, in which the movement of the arm need bear no definite relation to the number of the line with which it is desired to make connection therethrough, need not, therefore, be returned to normal and, in fact, does not have any normal position, but rests in the position where it was last used, the contact devices of the line cooperating with the connection terminals with the limbs of the line, however, being out of contact with such connection terminals. This construction is possible for the reason that 60 the contact arm *F* in its movement to find a

calling line sweeps over the terminals of all the lines until it finds the line which is calling, at which point, due to the energization of the relay *t* as hereinbefore described, it is stopped.

With regard to the selector switch on the contrary, it is necessary, prior to a second connection over the connecting circuit illustrated, that the selector arm *F'* be returned to its normal or false-zero position. This is readily accomplished, however, by the establishment of an energizing circuit for the stop relay *M'* due to the deenergization of the magnet *m* and the off-normal position of the contact-making wheel *R*. This circuit may be traced from the battery *e*, armature and back contact of the relay *m*, conductor 39, contacts *R''* and *R'*, stop magnet *M'*, to ground and back to battery. The magnet *M'* having been energized the clock-work mechanism will be free to move to drive the selector until it again reaches its normal or false-zero position, in which position the contact spring *R'* will again enter the depression in the periphery of the contact wheel *R*, thereby breaking the energizing circuit of the magnet *M'*, which by its deenergization prevents the further operation of the clock-work and stops the selector.

The deenergization of the relays *i* and *j* have restored normal connections of the connecting circuit and of the source of ringing current to the conductors 25 and 26. It will, however, be noted that no false signal will be given the substation B on account of the immediate deenergization of the magnet *G'*.

It will further be noted that the relays *q* and *p* which were locked up in the interval between the tens and units selection were deenergized by the deenergization of the relay *f* at the time of the energization of the relay *i*. It will be apparent, therefore, that all the apparatus is again restored to normal ready for a second call, a plurality of telephone lines being again associated with the first connecting circuit and its finder device by the retraction of the armature of the relay *v*, the circuit to which relay was broken by the retraction of the armature of the relay *m*.

Let us assume now that the subscriber B, with whom the subscriber A desires to obtain connection, has been already engaged in conversation in which case the relay *W* is maintained energized with its armature attracted. The subscriber A having stepped the selector arm around to the connection terminals of the line desired, in this instance the telephone line B, he opens the switch *b* and the circuit is closed from the battery *e*, conductors 10 and 35, armature and front contact of the relay *n*, conductor 40, relay *s*, relay *i*, back contact and armature of the

relay g , conductor 40, armature g' and front contact thereof of the relay g , primary winding h^2 of the induction coil h , conductor 31, contact device U^2 of the selector arm F' , connection terminal b^4 , conductor 33, armature and front contact of the relay W , condenser Y , conductor 45, busy-back X to ground and back to battery. Owing to the presence in this circuit of the condenser Y 5 10 no current from battery e will pass and the relays s and i will remain inert. The busy tone, however, on account of its alternating character will pass readily over this circuit, and in passing through the winding h^2 of 15 the induction coil h will introduce a similar and characteristic tone in the winding h' of the induction coil from which it will be transmitted to the calling subscriber over a 20 circuit which may be traced from the winding h' of the induction coil h through conductor 7, back contact and armature i' of relay i , relay j , contact device I upon the finder arm F , connection terminal a' , limb 1 of the telephone line A, receiver and transmitter of the substation A, when the subscriber removes his receiver from the hook, limb 2 of the telephone line, connection terminal a^2 , contact device I' of the finder arm 25 F , relay n , armature i^2 and back contact thereof of the relay i , conductor 8, relay k , relay g and back to the winding h' of the induction coil h . The subscriber A upon 30 hearing the busy tone in his receiver will be immediately aware that the line selected 35 is busy and will thereupon replace his receiver upon the hook, thereby, since both the switches b and b' are at this time open, restoring, as has been heretofore described, his entire apparatus to normal and ready for 40 another call.

In this connection it will be noted that the busy test circuit, both the circuit including the primary winding of the induction coil h and the secondary winding of such induction coil, will be maintained so long as the selected line remains busy and the subscriber at the calling line does not in the usual manner restore the apparatus to normal. By this means the calling subscriber cannot fail 45 to receive either the busy signal or the connection desired, should the line B become idle in the midst of the test.

If during the use of the connecting circuit, shown in full in the diagram in Figs. 6 50 and 7, by the subscriber's line A a second subscriber should desire a connection, the closure of the switches b and b' by such second subscriber at his substation will establish a circuit from the ground at such substation over the limb 1 of his line through 55 the armature and back contact of his cut-off relay (not shown), the armature and front contact of the relay v , conductor 43, armature and back contact of the lower relay 60 v , magnet m of the finder device associated

with the second connecting circuit, battery e and back to ground. The operation from this point to establish a connection for such second subscriber will then proceed precisely to the operation hereinbefore described in 70 establishing connection between the subscribers A and B. To the extreme left of Fig. 6 is diagrammatically shown the relation of the limb 1 to various telephone lines of the apparatus shown. It will be obvious 75 that should both the first and second connecting circuits be busy the two relays v would be energized and the limb 1 of the various lines would then be connected through the 80 armatures and front contacts of both of the relays v to the magnet M of a further connecting circuit.

It will be readily understood that the connections of each line in each of the finder devices will be simple multiples and that the connections to each line in each of the selector devices will be simple multiples, as indicated by the short branch wires leading from each of the fixed terminals of the switches shown in the drawings. Furthermore, the line terminals of each line are multiples in the first two connection terminals shown as a' , a^2 and b^2 , b^3 of each of the switches for the finder or selector. And the lowermost 90 terminals on the line finders and line connectors for each line are connected in multiple, as indicated in Figs. 6 and 7. In this manner each connecting circuit is adapted to 95 interconnect any two of the lines of the exchange. 100

While I have shown and referred to various batteries in connection with the system shown, it must be understood that where these batteries are of the same potential and polarity and located in the same exchange 105 they may be, and preferably are, one and the same battery.

While I have shown and described herein a particular form of my invention it must be understood that it is in no way restricted to the form herein shown, nor are any of the features thereof; but the invention as a whole or any of the features thereof, as defined by the claims, may be employed according to the engineering or traffic requirements of any particular case. 110 115

Having described my invention, what I claim and desire to secure by Letters Patent of the United States is:—

1. In a telephone exchange system, the combination with telephone lines extending to two sets of connection terminals, of a contact carrying arm associated with each said set of terminals, a connecting circuit connecting said arms, mechanism adapted when released to move said arms adjacent to the terminals of a calling and a called line, respectively, magnets adapted when energized to release said mechanisms, magnets adapted when energized to draw said arms 120 125 130 135

down upon the contacts of said lines, and circuits for said magnets controlled at the station of the calling line.

2. In a telephone exchange system, the combination with telephone lines terminating in groups of connection terminals, a finder device associated with each said group, a connecting circuit connected to each said finder device, an operating electromagnetic mechanism for said finder device to select the terminals of a line, a second electromagnetic mechanism adapted to bring said finder device into contact with such terminals, switching apparatus associated with each said line, circuits for said electromagnetic mechanisms controlled over said lines by said switching apparatus, a relay adapted to control the connection of the lines with said operating electromagnetic mechanism associated with one finder device and to transfer such connection to the operating electromagnetic mechanism of another finder device, and a circuit for said relay controlled by the second mentioned electromagnetic mechanism.

3. In a telephone exchange system, the combination with a plurality of telephone lines extending to terminals, of an automatic switching apparatus adapted to select the terminals of a line, holding mechanism to hold said switching apparatus in selective position, electromagnetic mechanism controlling said holding mechanism, a circuit for said electromagnetic mechanism including a source of current and a portion of each said line, a switch associated with each said line controlling said circuit, a connecting circuit connected to said automatic switching apparatus, a relay adapted to control the completion of the connection of said switching apparatus with the contact terminals of a selected line, a circuit for said relay adapted to be completed over a portion of each of said lines, and a second switch adapted to complete said circuit.

4. In a telephone exchange system, the combination with telephone lines extending to a plurality of groups of connection terminals, of switching apparatus associated with each said group, power mechanism adapted to operate each said switching apparatus to select terminals of a line, a stop mechanism normally preventing the movement of said switching apparatus, electromagnetic mechanism individual to each said stop mechanism for controlling said stop mechanism, an actuating circuit for said electromagnetic mechanisms including a source of current and a portion of each said telephone line, a switch associated with each said line controlling said circuit and mechanism adapted to connect said circuit with said electromagnetic mechanisms in succession, said mechanism being operated in the response of each said switching apparatus

to a call to transfer said actuating circuit to the electromagnetic mechanism of the next switching apparatus.

5. In a telephone exchange system, the combination with telephone lines extending to groups of terminals, switching apparatus associated with each said group, a connecting circuit connected to each said switching apparatus adapted to extend the circuit of said lines, electromagnetic mechanism for moving said switching apparatus over the associated group of terminals, electromagnetic mechanism adapted to arrest the movement of said switching apparatus and cause it to complete connection between a connecting circuit and one of said lines, a switch associated with each said line, a source of current, a circuit for said electromagnetic mechanisms including said source of current and the switch associated with the line the circuit of which is to be extended, a circuit for said electromagnetic mechanisms completed to each line in registering contacts of its connection terminals and said switching apparatus, a cut-off relay for each line adapted to disconnect from the line the circuits and mechanism for operating said switching apparatus, and a circuit for said relay closed by the connection to the line with which the relay is associated of a connecting circuit by means of said switching apparatus.

6. In a telephone exchange system, the combination with power mechanism, of a magnetic clutch controlling said power mechanism, a movable part adapted to be rotated by said power mechanism, a circuit for said magnetic clutch, a switch adapted to close said circuit initially to operate said clutch, and contacts closed by said movable part in its movement to maintain said circuit closed for a predetermined period of movement independent of said switch.

7. In a telephone exchange system, the combination with a switching device adapted to make tens and units selection, of a power apparatus for driving said switching device, an electromagnetic device controlling said power apparatus, a contact wheel, a circuit closer operated by said contact wheel to control the circuit through said electromagnetic device at intervals corresponding to the spaces of units selection, a second circuit closer operated by said contact wheel to control the circuit through said electromagnetic device at intervals corresponding to the spaces of tens selection, a switch adapted momentarily to operate said electromagnetic device, and means for making either of said circuit closers independently operable; whereby said arm may be advanced over predetermined spaces by momentary initial impulses.

8. In a telephone exchange system, the

- combination with a connection terminal support, telephone lines extending to connection terminals thereon, a contact carrying arm moving over said terminals, a contact tubular magnet carried by said support, and an armature carried by said arm, whereby said arm may be caused to make contact with the terminals of any line.
9. In a telephone exchange system, the combination with telephone lines extending to connection terminals, a connecting circuit, an automatic selector switch adapted to unite said connecting circuit with the connection terminals of any of said lines, said switch having a contact device adapted to move over said connection terminals in sequence and maintained normally and during its movement out of contact therewith, alternative controlling devices adapted to cause the movement of said switch over the contacts of ten lines or over the contacts of one line for each actuation, means controlled over a calling line to said connecting circuit for actuating said controlling devices the required number of times to move said contact device to select the connection terminals of any line, an electromagnet, an armature therefor secured to said contact device, said electromagnet when energized being adapted to move said contact device into engagement with the connection terminals of the selected line, and a circuit for said electromagnet controlled from the calling line.
10. In a telephone exchange system, the combination with telephone lines extending to connection terminals, of switching apparatus adapted to move over and make contact with said connection terminals, power mechanism operating said switching apparatus, an electromagnet controlling said power mechanism and normally preventing the movement of said switching apparatus, alternative controlling circuits for said electromagnet, circuit controlling devices to regulate the period during which said electromagnet shall continue energized to permit the movement of said switching apparatus, said circuit controlling devices being included one in each of said circuits and operated in the movement of said switching apparatus, and switching mechanism adapted to bring said controlling circuits alternately into operative relation with said switching apparatus.
11. In a telephone exchange system, the combination with a selector arm, of a magnet, and mechanism controlled thereby for moving said arm, a circuit for said magnet, controlling devices therefor, each said device when actuated maintaining said circuit completed a certain predetermined interval to permit said selector arm to move a predetermined distance, and means adapted to bring said controlling devices alternately into operative relation with the circuit of said magnet.
12. In a telephone exchange system, the combination with a group of connection terminals, of a selector arm adapted to move over said terminals, mechanism for moving said arm, alternative controlling mechanism for causing said arm to move in long and short steps, and means adapted to bring said controlling mechanisms into operative relation to said arm.
13. In a telephone exchange system, the combination with telephone lines extending to connection terminals, of a selector arm adapted to move over and make contact with said connection terminals, mechanism for moving said arm, electromagnetic mechanism adapted to control the starting and stopping of said arm, alternately controlling circuits for said electromagnetic mechanism, including contact devices operated in the movement of said arm, to control said electromagnetic mechanism to allow said contact arm to advance over a certain number of said connection terminals, the number of said connection terminals over which said arm may advance differing for the different controlling circuits.
14. In a telephone exchange system, the combination with telephone lines extending to a group of connection terminals, of a finder device adapted to rotate over said terminals, a connecting circuit terminating in contacts upon said device, a magnet M and mechanism controlled thereby controlling the rotation of said device, a circuit for said magnet adapted to be controlled over any one of said lines, a terminal a^3 associated with the connection terminals of each line and connected with one of the limbs of said line, a contact brush carried by said device and adapted in the movement thereof to trail over the terminal a^3 of said lines, a conductor including a magnet l and a source of current connected with said brush, a key associated with each line adapted as the contact brush of said device engages the terminal a^3 of such line to complete a circuit for the magnet l, a magnet G adapted when energized to move said device to bring the brushes carried thereby into engagement with the line whose key has been operated, and a circuit for said magnet G controlled by said magnet l.
15. In a telephone exchange system, the combination with telephone lines each extending to two groups of connection terminals, a switching device adapted to sweep over each said group of terminals, a connecting circuit uniting said switching devices, electromagnets M, G adapted to bring one of said switching devices into circuit with the terminals of any line, circuits for said magnets adapted to be controlled over each line, a magnet M^1 and mechanism con-

- trolled thereby for operating the other switching device, a relay g in a branch of said connecting circuit leading to a grounded source of current, a key associated with 5 each line adapted to ground the limb of the line connected with said branch, mechanism controlled by said relay g adapted to complete a circuit for the magnet M^1 to advance said other switching device over a predetermined 10 number of connection terminals, a magnet G^1 adapted to move said other switching device into engagement with the terminals of any desired line, and a circuit for said magnet controlled over the calling line.
16. In a telephone exchange system, the combination with telephone lines extending to groups of connection terminals, of a 15 finder arm associated with one of said groups, a selector arm associated with another of said groups, a connecting circuit uniting said arms, electromagnets M and G controlling the connection of the finder arm with the connection terminals of the several lines, 20 circuits for said magnets adapted to be controlled over any telephone line, a relay g connected with a source of current in a ground branch from said connecting circuit, means associated with each line for intermittently grounding the limb of the line connected through said connecting circuit with 25 said ground branch, a magnet M^1 controlling the movement of said selector arm, a circuit for said magnet adapted to be completed by said relay g , a part mounted to 30 rotate with the selector arm, said part having depressions upon its periphery at predetermined intervals, a spring bearing upon the periphery of said part, said spring having a contact from which it is separated 35 when resting in any one of said depressions, a locking circuit for said magnet M^1 closed by said part when rotated during the interval that the contact spring is passing from one depression to the next; whereby by one 40 manipulation of the substation key said selector arm may be moved over the connection terminals of a predetermined number of lines, a magnet G^1 adapted to draw said 45 selector arm into engagement with the terminals of any desired line, and a circuit for 50 said magnet G^1 controlled over a calling line.
17. In a telephone exchange system, the combination with telephone lines extending to two groups of connection terminals, of a 55 finder arm associated with one said group, a selector arm associated with the other said group, a connecting circuit uniting said arms, a pair of electromagnets controlling the connection of the finder arm with the terminals of any line, circuits for said 60 magnets controlled over any line in calling, electromagnetic mechanism controlling the 65 connection of the selector arm with the terminals of any line called, circuits for said mechanism controlled over the calling line, a source of ringing current, an electromagnetic switch controlling the connection of said source with a called line, and a circuit for said switch controlled over the calling line.
18. In a telephone exchange system, the combination with telephone lines extending to two groups of connection terminals, of 70 a finder arm associated with one of said groups, a selector arm associated with the other of said groups, a connecting circuit uniting said arms, electromagnets M^1 and G^1 controlling the connection of the selector arm with the terminals of any called line, circuits for said magnets controlled over the calling line, a relay u , armatures and their front contacts of said relay included in said connecting circuit, said armatures being connected directly with contacts upon said selector arm, a source of ringing current, the poles whereof are connected with the back contacts of said armatures, whereby when the selector arm makes 80 contact with the terminals of a called line ringing current is automatically applied thereto, a battery in bridge of said connecting circuit, a relay j included in said connecting circuit responsive to the switching apparatus associated with the calling line, a circuit for said relay u controlled by said relay j , said relay u being adapted when energized to disconnect said ringing current from said connecting circuit and 85 complete the circuit thereof.
19. In a telephone exchange system, the combination with a finder device comprising a terminal support, of telephone lines terminating in connection terminals carried by 90 said support, an arm carrying contact devices, power mechanism for rotating said arm adjacent said connection terminals, a stop device normally preventing the operation of said mechanism, a magnet controlling said stop device, and a magnet for which said contact arm forms the armature adapted to attract said arm and draw its contacts down upon the terminals of any 95 desired line.
20. In a telephone exchange system, the combination with telephone lines extending to groups of connection terminals, of a contact arm for each group, a connecting circuit associated with each arm, mechanism 100 adapted to move each arm over the connection terminals of each group, a magnet controlling each of said mechanisms, a conductor extending from one of the limbs of each of the telephone lines to a conductor 105 including said magnet of the first group, together with a source of current, a switch associated with each said line adapted to complete a circuit for said magnet to cause 110 the operation of the contact arm of the first 115

- group, a second magnet adapted to draw the contact arm against the terminals of any calling line, a circuit for said second magnet controlled over the calling line, and 5 means actuated in the completion of said circuit adapted to connect said conductors of each of the remaining lines with the first mentioned magnet of the second group of connection terminals, whereby if the contact 10 arm in the first group is employed in making connection with the calling line the next calling line will be selected by the contact arm of the second group or the contact arm of the first idle connecting circuit.
- 15 21. In a telephone exchange system, the combination with telephone lines extending to groups of connection terminals, a finder arm associated with each said group, a magnet for each group controlling the movement of said arm, a connecting circuit connected with each said arm, a conductor leading from a limb of each of the several lines to a conductor including said magnet of the first group of terminals and a source of current, switching apparatus associated with each said line adapted to complete the circuit of said magnet, a second magnet for each said contact arm adapted to complete the connection between said contact arm and 25 the terminals of any calling line, a circuit for said second magnet, switching apparatus associated with each line adapted to complete said circuit as the contact arm becomes adjacent the terminals of such line, a relay 30 m in said circuit and a relay v in a circuit controlled by said relay m , said relay v being adapted when energized to disconnect the said conductors leading from the several lines remaining inert from the said first 35 magnet of the finder arm in use and to connect said conductors with said first magnet of the next group of connection terminals.
- 40 22. In a telephone exchange system, the combination with telephone lines extending to two groups of connection terminals, a finder arm associated with one of said groups, a selector arm associated with the other of said groups, a connecting circuit adapted to unite said arms, a pair of electromagnets adapted to bring said finder arm into connection with the terminals of any calling line, a pair of electromagnets adapted to bring said selector arm into contact with any called line, a pair of relays adapted 45 to be associated with said connecting circuit and controlling the operation of said electromagnets associated with the selector arm, a second pair of relays adapted to disconnect said controlling relays from said connecting circuit, and switching apparatus associated with any calling line controlling circuits for said relays in proper sequence.
- 50 23. In a telephone exchange system, the combination with telephone lines extending to two groups of connection terminals, a 55 connecting circuit, a finder device connected to one end of said connecting circuit and associated with one said group, electro-magnetic mechanism for moving said arm into contact with the connection terminals 70 of a calling line and adapted to be controlled over such line, a selector arm connected with the other end of said connecting circuit and associated with the second said group of connection terminals, a magnet controlling the 75 movement of said selector arm over the connection terminals of such group, alternative controlling circuits for said magnet adapted to be operated over the calling line and including contact devices operated in the 80 movement of said selector arm, said contact devices being arranged with relation to said selector arm to control said magnet to allow said selector arm to advance over a predetermined number of said connection terminals, said predetermined number differing for the different controlling circuits, whereby said selector arm may be advanced to the 85 terminals of any desired line, a relay in a circuit adapted to be controlled over the calling line, a circuit for said magnet controlled by said relay upon the termination of conversation between two connected lines to return said selector arm to normal, and a contact device included in said last mentioned circuit and actuated upon the return of said selector arm to normal to open the 90 circuit of said magnet.
- 95 24. In a telephone exchange system, the combination with an escapement, of a shaft, power mechanism for driving said shaft, an electromagnetic clutch controlling said power mechanism, a movable part carried by said shaft, a circuit for said electromagnetic clutch, a switch adapted to close said circuit initially to operate said clutch, and a contact spring and its anvil associated with said movable part, said part having a number of depressions in its periphery located a predetermined distance apart, the end of said spring normally resting in one of said depressions out of contact with its anvil, said spring upon the movement of said part being forced out of said depression into engagement with its anvil to maintain the circuit of said clutch closed independent of said switch until it enters the next depression upon said part.
- 100 110 115 25. In a telephone exchange system, the combination with telephone lines extending to connection terminals, of a contact carrying arm adapted to sweep over said terminals, a contact on said arm being normally and during its advance out of engagement with said connection terminals, power mechanism for moving said arm, an electromagnet adapted to start said mechanism, an electromagnet adapted to stop said arm when it is adjacent the connection terminals of a calling line, said second electromagnet 120 125 130

- being adapted to draw said arm down to bring the contacts thereon into contact with connection terminals of such line, and circuits for said electromagnets controlled over said calling line.
26. In a telephone exchange system, the combination with an automatic selector switch carrying line terminals, of a contact carrying arm adapted to sweep over said terminals without engaging the same, means for advancing said arm over said terminals in long and short steps respectively, and means for moving said arm to bring the contacts thereon into connection with the terminals of the desired line.
27. In a telephone exchange system, the combination with a telephone line terminating in a central office, of a connecting circuit, automatic finder apparatus controlled over said line for uniting said connecting circuit therewith, an automatic selector switch carrying line terminals, a contact carrying arm associated with said connecting circuit and adapted to sweep over said line terminals, and means controlled over a calling line for advancing said arm in long and short steps respectively.
28. In a telephone exchange system, the combination with a telephone line, of a connecting circuit, automatic finder apparatus for uniting one end of said connecting circuit with said telephone line in response to a call, an automatic selector switch carrying line terminals, a contact carrying arm associated with said connecting circuit and adapted to sweep over said line terminals, and mechanism controlled from the calling line for advancing said arm in long and short steps respectively to the terminals of a desired line and connecting said connecting circuit with such line.
29. In a telephone exchange system, the combination with a telephone line, of a connecting circuit, automatic finder apparatus for uniting one end of said connecting circuit with said telephone line in response to a call, an automatic selector switch carrying line terminals, a contact carrying arm associated with said connecting circuit and adapted to sweep over said line terminals, means controlled from the calling line for advancing said arm to the terminals of a desired line, and means also controlled from the calling line for controlling the automatic application of ringing current to the desired line when said arm engages the terminals of such line.
30. In a telephone exchange system, the combination with an automatic selector switch, of line terminals thereon, a contact arm adapted to sweep over said terminals without contacting therewith, means for advancing said arm to the terminals of the desired line, means for bringing said arm into contact with such terminals and a source of ringing current automatically connected to said desired line upon the engagement of the contact arm with the terminals of such line.
31. In a telephone exchange system, the combination with a calling and a called telephone line, of a connecting circuit, automatic finder apparatus controlled over said calling line for uniting said connecting circuit with such line, an automatic selector switch controlled over said calling line for uniting said connecting circuit with said called line, and means automatically operated upon the completion of the operation of said selector switch and controlled over said calling line for applying ringing current to said called line.
32. In a telephone exchange system, the combination with an automatic selector switch carrying line terminals, of a contact arm adapted to sweep over said line terminals in long and short steps, and means automatically operated when said arm engages the desired line terminals for applying ringing current thereto.
33. In a telephone exchange system, the combination with an automatic selector switch carrying line terminals, of a contact arm adapted to sweep over said line terminals but out of engagement therewith, means for advancing said arm over said terminals in long and short steps, means for bringing said arm into contact with the terminals of the desired line, and means automatically operated when said arm makes contact with such terminals for applying ringing current thereto.
34. In a telephone exchange system, the combination with a group of line terminals, of a contact device adapted to move over said terminals, motor mechanism for moving said contact device, alternative controlling mechanism for regulating the distance of advance of said contact device, means adapted to bring said controlling mechanism into operative relation to said contact device, means adapted to effect the release of said contact device, and means for effecting the connection of said contact device with the desired terminals.
35. In a telephone exchange system, the combination with telephone lines extending to connection terminals, of a connecting circuit, a contact arm in which said connecting circuit terminates adapted to sweep over said connection terminals and successively make contact therewith, means for driving said arm, alternative controlling devices adapted to control the movement of said contact arm over a greater or less number of contacts for each actuation of said arm, and sender apparatus for controlling said alternative controlling devices and actuating said driving means.
36. In a telephone exchange system, the

combination with a calling and called telephone line, of a connecting circuit, automatic finder apparatus controlled over said calling line for uniting said connecting circuit with such line, an automatic selector switch controlled over said calling line for uniting said connecting circuit with said called line, a central source of ringing current, means automatically operated upon 10 the completion of the operation of said selector switch for applying said ringing current to said called line and electromagnetic means controlled over said calling line for cutting off said ringing current.

37. In a telephone exchange system, the combination with a calling and a called telephone line, of a connecting circuit, a switch for uniting said calling line with said connecting circuit, automatic selector 20 apparatus for uniting said connecting circuit with said called line, switching apparatus associated with the calling line adapted to control said selector apparatus, a central source of ringing current, means automatically operated upon the completion 25 of the operation of said selector apparatus for applying said ringing current to said called line, and electromagnetic means adapted to be controlled by said switching 30 apparatus for cutting off said ringing current.

38. In a telephone exchange system, the combination with an automatic selector switch carrying line terminals, of a contact 35 arm adapted to sweep over said line terminals, power mechanism for driving said arm, electromagnetic mechanism controlling the operation of said contact arm by said power mechanism, switching apparatus 40 controlling said electromagnetic mechanism, a central source of ringing current, means automatically operated when said arm engages the desired line terminals for applying said ringing current thereto, and means also controlled by said switching apparatus 45 for cutting off said ringing current.

39. In a telephone system, a telephone line, a plurality of rotary Y-switches in each of which said telephone line connects to 50 waiting contacts, a circuit adapted to be closed by control of the substation upon said telephone line and extending to the first of said Y-switches, and a relay in the first of said Y-switches to extend said circuit to the second of said Y-switches, substantially as described.

40. In a telephone system, a telephone line, a plurality of rotary Y-switches, a circuit adapted to be closed by control of said telephone line and extending to the first of said Y-switches, and a relay in the first of said Y-switches to extend such circuit to the second of said Y-switches, substantially as described.

41. In a telephone system, a plurality of

telephone lines, a plurality of rotary Y-switches in each of which said telephone lines are connected to waiting contacts, a circuit adapted to be closed by control of a substation upon any of said telephone lines 70 and extending to the first of said Y-switches, and a relay in the first of said Y-switches to extend said circuit to the second of said Y-switches, substantially as described.

42. In a telephone system, a telephone line, a plurality of trunks, automatic rotary Y-switches, one associated with each of said trunks, each adapted to connect its associated trunk to a calling telephone line, a circuit adapted to be closed by control of the substation upon said telephone line and extending to a first of said Y-switches, whereby when said circuit is closed by control of said substation, said first of said Y-switches will respond and connect its associated trunk 80 to said telephone line; other telephone lines adapted when calling to close said above mentioned circuit, an extension circuit extending from said first of said Y-switches to a second of said Y-switches, a relay in said first 90 Y-switch adapted to connect together said first mentioned circuit and said extension circuit when said Y-switch is busy, whereby, by the closure of said first mentioned circuit by control of a calling one of said telephone lines, said first Y-switch being busy, said first mentioned circuit will be closed through said extension circuit and said second of said Y-switches will respond and connect its associated trunk to said calling 100 telephone line.

43. An exchange system comprising telephone lines, switching mechanisms to which the lines are multiplied, said mechanisms each including a movable contact member, 105 means for giving each line control of any one of its switching mechanisms, and a unitary device individual to each switching mechanism for stopping its movable contact member after the same has been set 110 into movement and transferring the capability of control by the telephone lines from it to another switching mechanism.

44. In a telephone exchange system, a plurality of subscribers' lines and a number of automatic switches less than the number of subscribers' lines, a controlling circuit for said switches, controlling means for said circuit responsive to the closure of subscribers' lines in calling whereby a calling subscriber may operate an idle switch through said controlling circuit to cause the same to connect the switch with his line, and means controlled by said switch when actuated to disconnect itself from the controlling circuit and shift the control for succeeding calls to the next idle switch, substantially as described.

45. In a telephone system, a telephone line, a plurality of trunks, automatic rotary 130

Y-switches, one associated with each of said trunks, each adapted to connect its associated trunk to said telephone line when said telephone line is calling; a circuit, adapted to be closed by control of the substation upon said telephone line and extending to the first of said Y-switches, whereby when said circuit is closed by the control of said telephone substation, said first of said Y-switches will respond and connect its associated trunk to said telephone line; and a switch in said first Y-switch operating when said first Y-switch connects with said telephone line and operating to connect said circuit to the second of said Y-switches, substantially as described.

46. In a telephone system, a telephone line, a plurality of rotary Y-switches in each of which said telephone line connects to 20 waiting contacts, a circuit adapted to be closed by control of the substation upon said telephone line and extending to the first of said Y-switches, and means in the first of said Y-switches to extend said circuit, 25 to the second of said Y-switches, substantially as described.

47. In a telephone system, a telephone line, a plurality of rotary Y-switches, a circuit adapted to be closed by control of said 30 telephone line and extending to the first of said Y-switches and means in the first of said Y-switches to extend such circuit to the second of said Y-switches, substantially as described.

48. In a telephone system, a plurality of telephone lines, a plurality of rotary Y-switches in each of which said telephone lines are connected to waiting contacts, a circuit adapted to be closed by control of 40 a substation upon any of said telephone lines extending to the first of said Y-switches, a means in the first of said Y-switches to extend said circuit to the second of said Y-switches, substantially as described.

49. In a telephone system a plurality of telephone lines, a plurality of rotary Y-switches in each of which said telephone lines are connected to waiting contacts, a circuit adapted to be closed by control of a 50 substation upon any of said telephone lines and extending to the first of said Y-switches, a means in the first of said Y-switches to extend each circuit to the second of said Y-switches when said first Y-switch has its 55 wipers in connection with the waiting contacts of a busy telephone line, substantially as described.

50. An exchange system comprising a central station, telephone lines extending thereto, progressively traveling switching mechanisms to which the lines are connected, a unitary device individual to each line for controlling any one of its progressively traveling switching mechanisms, and means 60 individual to each switching mechanism for

transferring the line control from it to another progressively traveling switching mechanism.

51. An exchange system comprising telephone lines, switching mechanism having 70 movable contact members and to which the lines are multiplied, means for giving each line control to any one of its switching mechanisms, means for starting a switching mechanism thus controlled, and means individual to said switching mechanism for stopping its movement after it has been started and transferring the capability of control from it to another switching mechanism. 75

52. In an exchange system, the combination with a plurality of finder switches, each provided with stationary and movable terminals and each having a connecting circuit associated with the movable terminals thereof, of a plurality of telephone lines multiplied to the stationary terminals of said switches, switching apparatus associated with each line and made operative in the initiation of a call therein, said apparatus being adapted to change the electrical condition of a stationary terminal associated with said line on each of said finder switches, electrically operated mechanism controlled by said switching apparatus and adapted to cause the movable terminals of a finder switch to traverse the stationary terminals thereof, a relay associated with the movable terminals of said finder switch, said relay being responsive to the changed electrical condition of the terminal of a calling line when connection is made therewith, and means controlled by said relay adapted to again change the electrical condition of the aforesaid changed stationary terminals of said line on each of said switches, whereby other switches are prevented from completing connection with the calling line. 95

53. In an exchange system, the combination with a plurality of lines and a line finder therefor, said line finder being adapted to rest normally in connection with the terminals of any of said lines, of motor mechanism for said line finder, calling mechanism for each line adapted when actuated to energize said motor mechanism and at the same time to change the electrical condition of the line calling, and means operating when the line finder makes connection with said line for deenergizing said motor mechanism. 110

54. In an exchange system, the combination with a group of lines, of a plurality of connecting circuits each having an automatic switch adapted to make connection with any of said lines, a motor mechanism for each switch, controlling apparatus for each line adapted when actuated to change the electrical condition of said line and to energize the motor mechanism of an idle switch 115

causing the same to test the lines in succession, and automatic mechanism operating when test is made of said line to deenergize said motor mechanism and to transfer the 5 remaining lines into operative relation to the motor mechanism of another idle switch.

55. In an exchange system, the combination with a group of lines, of a plurality of connecting circuits each having an automatic switch adapted to make connection with any of said lines, a motor mechanism for each switch, controlling apparatus for each line adapted when actuated to change the electrical condition of said line and to energize 10 the motor mechanism of an idle switch causing the same to test the lines in succession, and automatic means operating when test is made of said line to deenergize said motor mechanism, to again change the electrical 15 condition of said line and to transfer the remaining lines into operative relation to the motor mechanism of another idle switch.

56. In a telephone exchange system, the combination with a plurality of subscribers' 20 lines, of a plurality of connecting circuits each having an automatic switch adapted to make connection with any of said lines, a motor mechanism for each switch, controlling apparatus at the substation of each line adapted when the subscriber thereof is calling 25 to change the electrical condition of said line and to energize the motor mechanism of an idle switch to cause the same to test said lines in succession, and automatic means operating 30 when test is made of the line calling to deenergize said motor mechanism and to transfer the remaining lines into operative relation to the motor mechanism of another idle switch.

57. In an exchange system, the combination with a plurality of lines, of a plurality of connecting circuits each having an automatic switch adapted to make connection with any of said lines and one of said 40 switches being normally in operative relation to all of said lines, a motor mechanism for each switch, controlling apparatus for each line adapted when actuated to change the electrical condition of said line and to energize the motor mechanism of said switch 45 to cause the same to test the lines in succession, and automatic means operating when test is made of said line to deenergize said motor mechanism and to transfer the remaining lines into operative relation to the motor mechanism of another automatic switch.

58. The combination with a series of terminals and a finder brush adapted to traverse said terminals in sequence, of a magnet for controlling the movement of said finder brush, a switch mechanism associated with each terminal for placing a test condition thereon and for controlling the circuit of 55 said magnet, another magnet connected to

said finder brush for arresting the travel thereof at any terminal placed in test condition, said finder brush being adapted to be moved out of its arrested position over one terminal and into position over another terminal under the control of the associated switch mechanism of the latter. 70

59. The combination with a plurality of lines, of switches in which said lines are multiplied, a progressively advancing finder 75 brush for each switch, a magnet for each finder brush for controlling its movement, mechanism for each line adapted when actuated to complete a circuit for a finder brush magnet and also to place the multiple 80 terminals of a line in selectable condition, another magnet for each finder brush for arresting its movement when it comes into engagement with a multiple terminal in selectable condition, said finder brush being advanced out of its arrested position into engagement with the terminal of another line under the control of the latter. 85

60. The combination with a series of terminals and a finder brush adapted to traverse said terminals in sequence, of manually operated key mechanisms connected to corresponding terminals in the path of said finder, means controlled by any mechanism for moving said finder brush over said terminals, means controlled by said mechanism for establishing a circuit which may be completed by said finder brush in engaging the terminal corresponding to such mechanism, a magnet in said circuit and means operated 95 by said magnet for arresting the travel of said finder brush, which is adapted to be moved out of its arrested position under control of the key mechanism of another terminal. 100

61. The combination with a point finder apparatus having a series of terminals and a finder brush resting normally in any position and adapted to traverse said terminals in sequence, switching mechanisms corresponding to the different terminals, means controlled by any switching mechanism when actuated for setting said point finder in operation, means controlled by the different switching mechanisms for selectively determining the limit of operation of said point finder and means dependent upon the condition of a connection established at one terminal for preventing the switching mechanism of another terminal from again setting said point finder in operation. 110

62. The combination with a point finder apparatus having a series of terminals and a brush adapted to traverse said terminals in sequence, said brush being arranged to rest normally in connection with any of said terminals, of switching mechanisms corresponding to the different terminals, means controlled by any switching mechanism 125 when actuated for setting said point finder 130

- in operation, a translating device actuated when said finder brush makes connection with the terminal associated therewith, and means dependent upon the condition of a connection established at one terminal for preventing the switching mechanism of another terminal from again setting said point finder in operation.
63. The combination with a point finder apparatus having a series of terminals and a finder brush adapted to traverse said terminals in sequence and arranged to rest normally in connection with any of said terminals, of keys corresponding to the different terminals, means controlled by any key when actuated for setting said point finder in operation, means associated with the different keys for selectively determining the limit of operation of said point finder, and means dependent upon the condition of a connection established at one terminal for preventing the key of another terminal from again setting said point finder in operation.
64. The combination with a point finder apparatus having a series of terminals and a finder brush adapted to traverse said terminals in sequence and arranged to rest normally in connection with any of said terminals, of keys corresponding to the different terminals, means controlled by any key when actuated for setting said point finder in operation, a translating device operated when the point finder makes connection with the terminal corresponding to the actuated key, and means dependent upon the condition of a connection established at one terminal for preventing the key of another terminal from again setting said point finder in operation.
65. In an exchange system, the combination with a plurality of lines and a selector having terminals of said lines and a contact arm adapted to sweep over said terminals, of power mechanism for advancing said arm, an electromagnet for controlling the operation of said power mechanism, controlling apparatus for governing the energization and deenergization of said electromagnet to cause said arm to advance to the terminal of a desired line and to hold the connection thus made, and a switch associated with said selector open in the normal and closed in the off-normal position thereof, said switch cooperating with said calling mechanism to control the energization and deenergization of said electromagnet to cause a further advance movement of said arm to normal.
66. A telephone system including telephone lines, a source of calling current, switch contacts operatively connected to said source, an electromagnet controlling said contacts, a selector, test means for said selector operative according to the busy or idle condition of a wanted line, means for applying said test means to a contact of said line on selection thereof, and a circuit for said electromagnet under the exclusive control of said test means and made operative thereby to control said electromagnet to govern the connection of said source with the wanted line.
67. In a telephone exchange system, the combination with telephone lines and a source of calling current, of switch contacts operatively connected to said source, an electromagnet controlling said contacts, a selector, a test relay for said selector operative according to the busy or idle condition of a wanted line, means for applying said test relay to a contact of the called line on selection thereof, and a circuit for said electromagnet adapted to be controlled exclusively by said relay to cause said electromagnet to govern the connection of said source with the wanted line.
68. In a telephone exchange system, the combination with telephone lines and a source of calling current, of a selector having test contacts of the lines and a test brush adapted to trail over said contacts, a test relay adapted to be connected to said brush and operative according to the busy or idle condition of the wanted line, a switch for closing the circuit of said test relay on selection of said line, switch contacts operatively connected to said source, an electromagnet controlling said contacts, and a circuit for said electromagnet adapted to be controlled exclusively by said test relay to govern the connection of said source with the wanted line.
69. In a telephone exchange system, the combination with a plurality of lines, of a selector, a single motor means therefor, a calling mechanism, a pair of devices associated with said motor means and cooperating with the calling mechanism to govern the movement of the selector in long and short steps respectively, and transfer mechanism for shifting the operative relation of said calling mechanism from one of said devices to the other.
70. In a telephone exchange system, the combination with a plurality of lines, of a selector, a single motor means therefor, a calling mechanism, a pair of electrical devices associated with said motor means and cooperating with the calling mechanism to govern the movement of the selector in long and short steps respectively, and a relay adapted under the control of said calling mechanism to shift the connection of the selector from one of said devices to the other.
71. In a telephone exchange system, the combination with a plurality of lines and a selector therefor, of calling mechanism, a pair of interrupters actuated by the movement of the selector and cooperating with the calling mechanism to govern selection,

- and transfer mechanism operating under the control of said calling mechanism and adapted to shift the operative relation of the calling mechanism from one of said interrupters to the other. 65
72. In a telephone exchange system, the combination with a plurality of lines and a selector therefor, of calling mechanism, a motor magnet adapted when energized to cause a continuous advance movement of the selector, a pair of electrical devices for governing the circuit of said motor magnet and adapted to measure the advance movement of the selector in long and short steps, 70
- 10 respectively, and transfer mechanism operating under the control of the calling mechanism for shifting the connection of said motor magnet from one of said devices to the other. 75
- 15 73. In a telephone system the combination with a calling and a called line, of a connecting circuit therefor, a connecting circuit test terminal, a called line test terminal, automatic means for directly bringing them into contact, test means associated with said connecting circuit test terminal operative according to the busy or idle condition of the called line, a source of ringing current associated with said connecting circuit, and 80
- 20 means under the control of said test means whereby ringing current automatically will be sent to the called line depending only upon its idle condition. 85
- 25 74. In a telephone system the combination with a calling and a called line, of a connecting circuit therefor, a connecting circuit test terminal, a called line test terminal, automatic means for directly bringing them into contact, test means associated with said connecting circuit test terminal operative according to the busy or idle condition of the called line, a source of ringing current associated with said connecting circuit, means under the control of said test means whereby ringing current automatically will be sent to the called line depending only upon its idle condition, and a busy tone likewise associated with said connecting circuit and adapted to send back a busy signal to the calling line if said test means finds the called line busy. 90
- 30 75. In a telephone system the combination with a calling and a called line, of a connecting circuit therefor, a connecting circuit test terminal, a called line test terminal, automatic means for directly bringing them into contact, a source of ringing current and a test means both associated with said connecting circuit, and means for connecting the former in circuit with the called line immediately upon the operation of the latter. 95
- 35 76. In a telephone system the combination with a calling and a called line, of a connecting circuit therefor, a connecting circuit test terminal, a called line test terminal, automatic means for directly bringing them into contact, a source of ringing current and a test means both associated with said connecting circuit, the latter operative according to the busy or idle condition of the called line, means for connecting the former in circuit with the called line immediately upon the operation of the latter, and a busy tone likewise associated with connecting circuit and adapted to send back a busy signal to the calling line if said test means finds the called line busy. 100
- 40 77. In a telephone system the combination with a calling and a called line, of a connecting circuit adapted automatically to complete a talking circuit between said lines, automatic test means for determining the busy or idle condition of said called line, and a source of ringing current, both associated with said connecting circuit, and means exclusively under the control of said test means for connecting said source of ringing current in circuit with the called line upon determining its idle condition. 105
- 45 78. In a telephone system the combination with a calling and a called line, of a connecting circuit adapted automatically to complete a talking circuit between said lines, automatic test means for determining the busy or idle condition of said called line, and a source of ringing current, both associated with said connecting circuit, means exclusively under the control of said test means for connecting said source of ringing current in circuit with the called line upon determining its idle condition, and a busy tone likewise associated with said connecting circuit and adapted to send back a busy signal to the calling line if said test means finds the called line busy. 110
- 50 79. In an automatic switch, the combination with a movable member, of a motor means, a circuit over which said motor means initially is made active to cause the movement of said movable member, an auxiliary circuit over which said motor means may be maintained active, contacts of said auxiliary circuit closed by the movement of said movable member during a predetermined movement thereof, whereby said movable member may be advanced a fixed distance independently of the initial circuit. 115
- 55 80. A telephone system including telephone lines, link circuits at the exchange having electrically operated selective switches at both ends, the switches at the answering ends of said link circuits serving when started to connect link circuits with calling lines, a starting conductor operatively associated with all said lines and responsive to each call to initiate travel of one idle switch only of said last mentioned selective 120
- 60 125

switches, and means whereby calling subscribers may vary the connections of said conductor at any time.

81. A telephone exchange system comprising a plurality of subscribers' telephone lines, interconnecting link circuits, means, including electrically controlled switches, for connecting said link circuits so as to establish conversational connection between calling and called lines, metallic circuits extending from the central office to each substation, and means whereby one of the connected substations, independently of the other substation, may restore said switches to normal by breaking said metallic circuit.

82. A telephone system including metallic circuit lines, a link circuit having a selective switch at its end adjustable responsive to directive current impulses to connect one line with another, electromagnetic release means for said switch capable of being operated solely by the opening of the metallic circuit at a connected substation.

83. A telephone system including telephone lines, selective switches at the exchange adapted to connect one of said lines with another for conversation, a release control relay for said selective switches held energized during conversation, means controlled by the opening of a metallic circuit of a connected telephone line to operate said relay, and means controlled solely by such operation of said relay to restore said switches to normal.

84. A telephone system including a pair of connected telephone lines, selective switches included in connection between said lines, and means automatically operated by the opening of the metallic circuit of one only of said lines to restore said switches to normal.

85. A telephone exchange system comprising a plurality of subscribers' telephone lines, suitable substation equipments, interconnecting link circuits, means, including electrically controlled switches, for connecting said link circuits so as to establish conversational connection between calling and called lines, and means whereby the restoration of the receiver at one of the connected substations prior to the restoration of the receiver at the other will interrupt a metallic circuit extending to the first substation and thereby restore said switches to normal.

86. A telephone exchange system comprising a plurality of subscribers' telephone lines, interconnecting link circuits, means, including electrically controlled switches, for connecting said link circuits and lines into conversational circuits, and means for restoring the switches to normal by the interruption of the conversational circuit at one of the connected substations while leav-

ing the conversational circuit at the other 65 substation closed.

87. In a telephone exchange system the combination with a connecting circuit and an automatic selector, of a busy back apparatus, a ringing generator, a test relay, a test circuit therefor, said relay being adapted in alternate positions of its armature to bring said busy back apparatus and said ringing generator into operative relation to a talking strand of said connecting circuit. 75

88. In a telephone exchange system, the combination with a connecting circuit and an automatic selector, of a busy back apparatus, a ringing generator, a test relay having front and back contacts, a test circuit 80 therefor, local circuits for said busy back apparatus and said ringing generator, and switching mechanism adapted upon the closure of said back and front contacts to bring said busy back apparatus and said ringing 85 generator, respectively, into operative relation to a talking strand of said connecting circuit.

89. A group of telephone lines, which may be calling lines; a line selector common to said group; a cut-off terminal in said line selector for each line; a final selector; a cut-off terminal in final selector for each of said lines; a cut-off relay and circuit for each of said lines; electric connections from said line selector, and final selector terminals to their individual cut-off relays; means operated by calling line to energize the cut-off relay of his own line through the cut-off terminal upon assuming control of a line 100 selector; and means operated by said calling line, to energize the cut-off relay of the called line in the final selector through its individual cut-off terminal; all designed for the purpose of causing a calling party to 105 first disconnect his own line and also the line selector temporarily connected thereto from all connections common to other lines, and finally to disconnect the called line from all common connections, thus isolating the two 110 connected lines from all others.

90. An automatic telephone system including a calling line and a called line, a circuit connecting said lines, a link circuit included therein having normally open contacts, a central source of current, an electromagnet sensitive to the idle condition of the called line for automatically closing said contacts to supply current to the calling line, a second electromagnet, and means at a substation for controlling said second magnet to open said contacts. 115

91. A telephone system including telephone lines having test terminals adapted to be differently connected according to the busy or idle condition of the lines, a test wiper for engaging said test terminals, a switch in circuit with said wiper and

- adapted to establish connections dependent upon the busy or idle condition of the encountered line, an electromagnet sensitive to the busy or idle condition of the tested line for controlling said switch, a circuit controlling relay adapted to be cut in circuit by said switch only if the encountered line is idle, and a second electromagnet for releasing said switch.
92. A telephone system including a calling line and a called line, a link circuit common to a plurality of lines, relays therefor adapted to be operated by currents flowing over a calling telephone line, talking conductors therefor having normally open contacts, an electromagnet for closing said contacts, a ringing relay, and means for operating said magnet and said relay automatically controlled by the idle or busy condition of the called line.
93. An automatic telephone system comprising a plurality of lines extending from substations to an exchange, calling and called contacts for said lines at the exchange, link circuits and electrically operated switching mechanism for establishing connection from the calling contacts of a calling line to the called contacts of an idle line, a relay for destroying the normal operative relation of said called line with its calling contacts, means operative upon the engagement of said switching mechanism with said called line contacts to actuate said relay and to automatically supply ringing current to said called line by completing a circuit through one of the engaged called line contacts.
94. A telephone system comprising a plurality of lines extending from substations to an exchange, calling and called contacts for said lines at the exchange, the former contacts being normally connected to said line, link-circuits for interconnecting calling and called lines, electrically operated switching mechanism for establishing a connection between the calling contacts of a calling line and one end of an idle link circuit, means for connecting the other end of said link circuit to the called contacts of an idle called line, a relay for destroying the normal connection of said called line with its calling contacts, and means operative upon the connection of said link-circuit to said called line contacts to actuate said relay by completing a circuit through one of the engaged contacts of said line.
95. A telephone system comprising a plurality of lines extending from substations to an exchange, calling and called contacts for said lines at the exchange, link-circuits for interconnecting calling and called lines, electrically operated switching mechanism for establishing a connection between the calling contacts of the calling line and one end of an idle link-circuit, means for connecting the other end of said link circuit to the called contacts of an idle called line, a relay for destroying the normal connection of said called line with its calling contacts, a relay for completing a portion of the connected normally discontinuous link-circuit, and means to actuate said relays by completing the circuit through one of the engaged called line contacts upon the connection of said link-circuit to said called line contacts.
96. A telephone system comprising telephone lines extending from substations to an exchange, terminal contacts for each of said lines, a link-circuit for interconnecting the said contacts of calling and called lines to establish a talking circuit therethrough, an interrupter for causing a busy signal, a relay for controlling the connection of said interrupter to the calling line circuit, means for momentarily energizing said relay to cause its actuation, and means for completing a locking circuit for said relay through one of the contacts of said called line.
97. An automatic telephone system comprising a plurality of lines extending from substations to an exchange, calling and called contacts for said lines at the exchange, link circuits and electrically operated switching mechanism for establishing connection from the calling contacts of a calling line to the called contacts of an idle line, a relay for destroying the normal operative relation of said called line with its calling contacts, means for supplying ringing current, a relay for controlling the application of said ringing current to said called line, means to actuate said relays by completing a circuit through one of the engaged called line contacts upon the engagement of said switching mechanism with said called line contacts.
98. A telephone system comprising a plurality of lines extending from substations to an exchange, calling and called contacts for said lines at the exchange, normally discontinuous link circuits for interconnecting calling and called lines, electrically operated switching mechanism for establishing connection between the calling contacts of the calling line and one end of an idle link-circuit, means for connecting the other end of said link-circuit to the called contacts of an idle line, a relay for destroying the normal connection of said called line with its calling contacts, a relay for completing a portion of the connected normally discontinuous link-circuit, and means to actuate said relays by completing the circuit through one of the engaged called line contacts upon the connection of said link-circuit to said called line contacts.
99. A telephone system comprising a plurality of lines extending from substations to an exchange, calling and called contacts for said lines at the exchange, link circuits and electrically operated switching mechanism for establishing connection between the calling contacts of the calling line and one end of an idle link-circuit, means for connecting the other end of said link circuit to the called contacts of an idle called line, a relay for destroying the normal connection of said called line with its calling contacts, a relay for completing a portion of the connected normally discontinuous link-circuit, and means to actuate said relays by completing the circuit through one of the engaged called line contacts upon the connection of said link-circuit to said called line contacts.

tacts for said lines at the exchange, link circuits for interconnecting calling and called lines, electrically operated switching mechanism for establishing a connection between the calling contacts of a calling line and one end of an idle link-circuit, means for connecting the other end of said link-circuit to the called contacts of an idle line, a relay for destroying the normal operative relation of said called line with its calling contacts, means for supplying ringing current, a relay for controlling the application of said ringing current to said called line, and means to actuate said relays by completing a circuit through one of the engaged called line contacts upon the connection of said link-circuit to said called line contacts.

100. In a telephone system, the combination with an automatic switch having a plurality of stationary terminals and a movable terminal adapted to traverse the same, of electrically controlled mechanism for causing the movement of said movable terminal over said stationary terminals, an energizing circuit for said switch controlling mechanism, a contact device for closing said energizing circuit to cause the movement of said movable terminal, and contacts associated with said automatic switch and operated in the movement of the movable terminal thereof, said contacts being adapted to close said energizing circuit independently of the aforesaid contact device while the movable terminal is traversing the spaces between adjacent stationary terminals, whereby the stopping of said movable terminals upon a stationary terminal of the switch is ensured.

101. In a telephone system, the combination with a switch adapted to occupy a number of operative positions, of electrically controlled mechanism for imparting to said switch a movement to move it through its various operative positions, an energizing circuit for said switch-controlling mechanism, a contact device for controlling said energizing circuit to determine the degree of movement of said switch, and switching mechanism associated with said switch and adapted in the movement thereof to maintain said energizing circuit closed independently of the aforesaid contact device while the switch is moving from one to another of its positions.

102. In a telephone system, the combination with a telephone line, of an automatic switch having a movable terminal to which said telephone line is connected, a plurality of stationary terminals, electrically controlled means for moving said movable terminal over said stationary terminals, a calling device at the other end of the telephone line, switching mechanism associated with said automatic switch and adapted to

be actuated as the movable terminal moves into contact with each stationary terminal in the movement of the switch, and an energizing circuit for said switch-controlling means, said circuit being under the joint control of said switching mechanism and said calling device, and being adapted to be placed under the sole control of said calling device upon each actuation of said switching mechanism when the movable terminal is upon the stationary terminal.

103. In a telephone system, the combination with a telephone line, of an automatic switch having a movable terminal to which said line is connected, a plurality of stationary terminals, electrically controlled means for moving said movable terminal over said stationary terminals, an energizing circuit for said controlling means, switch mechanism actuated in the movement of said automatic switch and adapted to render said energizing circuit active intermittently to cause the movement of said movable terminal across the spaces separating said stationary terminals from each other, and manually controlled means for rendering said energizing circuit active during the intermissions of activity produced by the operation of said switch mechanism, to cause the movable terminal to pass over certain of said stationary terminals.

104. In a telephone system, the combination with a telephone line, of an automatic switch having a movable terminal upon which said telephone line terminates, a plurality of stationary terminals for said switch upon which other lines terminate, means for moving said movable terminal over said stationary terminals, means for stopping the movement of said movable terminal, switching mechanism controlling said stopping means, said switching mechanism being adapted to be made operative in the movement of the switch only when the movable terminal is in contact with a stationary terminal, and a calling device adapted to render said switching mechanism ineffective to stop the movement of the movable terminal as it passes over certain ones of said stationary terminals.

105. In a telephone system, the combination with a line terminating in an automatic switch having a movable terminal and a plurality of stationary terminals to which other lines are connected, of a calling device adapted to be associated with said line, an intermittently acting switch operating in the movement of said movable terminal over said stationary terminal, a divided circuit, actuating means for said movable terminal, controlling means therefor maintained active over said divided circuit, and means for placing one branch of said circuit under the control of the calling

device as soon as a movable terminal engages a stationary terminal and the other branch under the control of the intermittently acting switch of the movable terminal when the latter is traversing the space between adjacent stationary terminals, whereby said movable terminal is prevented from stopping between stationary terminals, but may be stopped by the calling device immediately 10 said movable terminal engages a predetermined stationary terminal.

106. In a telephone system the combination with a telephone line terminating in an automatic switch having a plurality of 15 stationary terminals connected to other lines and a movable terminal, actuating means therefor, an intermittently acting switch actuated in the movement of said movable terminal over said stationary terminals, a calling device, means for bringing said actuating means into operation, and means for maintaining said actuating means active while said movable terminal is traversing stationary terminals, controlled in 25 said calling device only when a movable terminal engages a stationary terminal and in said intermittently acting switch when said movable terminal passes between stationary terminals.

107. In a telephone system the combination with a telephone line terminating in an automatic switch having a plurality of 30 stationary terminals connected to other lines and a movable terminal, actuating means therefor, an intermittently acting switch actuated in the movement of the said movable terminal over said stationary terminals, a calling device, means for bringing said actuating means into operation and 35 for maintaining said actuating means active controlled in said calling device only when the movable terminal is at normal or when it engages a stationary terminal and in said intermittently acting switch when 40 said movable terminal passes between stationary terminals.

108. In a telephone exchange system, a switch comprising stationary terminals and a movable terminal, an electromagnet controlling the movement of said movable terminal, an energizing circuit therefor, an 45 interrupter in said circuit, and means operated in the movement of said movable terminal over said stationary terminals for intermittently operating said interrupter so as to maintain said energizing circuit in 50 operative condition while said movable terminal is passing from one stationary terminal to another.

109. In a telephone exchange system, a switch comprising stationary terminals and a movable terminal, an electromagnet for controlling the movement of said movable terminal, a divided circuit for energizing 55 said magnet, a calling device, controlling

means in one branch of said circuit, an interrupter in the other branch of said circuit, and means for closing said interrupter each time said movable terminal traverses the space between adjacent stationary terminals, whereby said movable terminal can stop only when in engagement with one of said stationary terminals.

110. The combination with a finder switch having a progressively advancing contact member, of a plurality of lines extending to terminals of said finder switch, means under control of one of said lines for causing the contact member to advance to and stop upon the terminal of said line and subsequently under the control of another one of said lines to leave the terminal of said first line and to advance to and stop upon the terminal of said second line, and means dependent upon the condition of said first named line for preventing said second named line from controlling the advance of the contact member.

111. The combination with a finder switch having a movable member, of a plurality of lines extending to terminals thereof, means under the control of one of said lines to cause the movable member of said finder switch to engage the terminal of said line and subsequently under the control of another one of said lines to disengage said first named terminal and engage the terminal of said second line, and means dependent upon the first established connection for preventing said second line from controlling the movable member of said switch.

112. The combination with a plurality of lines, of two or more finder switches in which said lines are multiplied, a progressively advancing contact member for each of said finder switches, means for altering the electrical condition of the multiple terminals of a line to stop a contact member of one of said switches in engagement with one of the multiple terminals of said line, and means acting coincident with the changed condition of the multiple terminals of another line for causing said contact member to advance from its arrested position into engagement with a multiple contact of said second line.

113. The combination with a plurality of lines, of two or more finder switches in which said lines are multiplied, a movable contact member for each of said finder switches, a link circuit for each movable member, means for altering the electrical condition of the multiple terminals of a line to stop a contact member of one of said switches in engagement with one of the multiple terminals of said line, and means acting coincident with the changed condition of the multiple terminals of another line for causing said contact member to move out

of engagement with said first line and into engagement with a multiple terminal of said second line, and means dependent upon the first established connection for preventing said second line from controlling said movable member.

114. In a telephone exchange system, the combination with a connecting circuit and an automatic selector, of a busy-back apparatus, a ringing generator, and automatic means dependent only upon the busy or idle condition of a called line for bringing said busy-back apparatus or said ringing generator into operative relation to a talking strand of said connecting circuit.

115. In an automatic switch, the combination with a plurality of stationary terminals, of a movable contact member, motor means therefor, an electromagnet for controlling the movement of said contact member, a circuit for said electromagnet having two co-operating points of control, one for governing the initial movement of said contact member and the other for insuring the continued movement of said contact member from one stationary terminal to another.

116. In a switch, the combination with a plurality of stationary terminals, of a movable contact member, means for controlling the initial movement of said contact member, and means cooperating with said first named means for insuring the continued movement of said contact member from one stationary terminal to another independent of the control exercised by said first named means.

117. In an exchange system, the combination with a group of lines, of a plurality of connecting circuits over which simultaneous talking connections between lines in the same group may be established, a plurality of line finders each forming the terminal of a connecting circuit, multiple test contacts in each finder switch one for each line, controlling apparatus adapted when actuated to change the electrical condition of the multiple test contacts individual to a calling line and to cause one of said line finders to extend the circuit of that line to a connecting circuit, and automatic means for again changing the electrical condition of said multiple test contacts when the line finder makes connection with said line, whereby other line finders are prevented from making connection with that line.

118. In a telephone system, the combination with a group of lines, of a lesser plurality of progressively traveling line finder switches each line being multiplied to each of said finder switches, a starter wire to which all of said lines are electrically connected and which though normally directly connected to one of said finder switches may be extended directly to each of the other finder switches, means whereby any one of said

lines in calling may start a finder switch into operation over said starter wire, means made operative when the progressively traveling member of the finder switch so started establishes connection with a calling line for extending said starter wire to another one of said finder switches so that any one of the remainder of said lines may upon calling immediately start that finder switch into operation without disturbing the first established connection, and means for preventing an answered calling line from interfering with the progressive travel of a subsequently started finder switch.

119. In a telephone system, the combination with a group of lines, of a lesser plurality of progressively traveling line finder switches each line being multiplied to each of said line finders, a starter wire normally directly connected to an idle line finder so as to place it under the direct control of each of said lines, means operated over said starter wire whereby any one of said lines in calling may start said line finder, means for arresting the progressive travel of said line finder when it reaches the calling line, and means controlled by the operation of said line finder for extending the starter wire directly to another idle line finder so that it may be started into operation when another line calls.

120. A telephone exchange system comprising telephone lines terminating in waiting contacts, other telephone lines terminating in groups of waiting contacts, a link circuit provided with a traveling terminal at each of its two extremities, automatic switching mechanism for connecting said link circuit to any one of said first mentioned telephone lines by moving one of said traveling terminals to engagement with the contact corresponding to such line, and automatic switching mechanism for connecting said link circuit to any one of said other telephone lines comprising means primarily adjusted for advancing the other of said traveling terminals to the group of contacts and secondarily adjusted for advancing said terminal to engagement with the contact in the group corresponding to such other telephone line.

121. A telephone exchange system comprising telephone lines terminating in waiting contacts, other telephone lines terminating in groups of waiting contacts, a group of link circuits each provided with a traveling terminal at each of its two extremities, means for isolating an idle one of said link circuits, automatic switching mechanism for connecting the isolated link circuit to any one of said first mentioned telephone lines by moving one of its traveling terminals to engagement with the contact corresponding to such line, automatic switching mechanism for connecting said isolated link

5 circuit to any one of said other telephone lines comprising means primarily adjusted for advancing the other of its traveling terminals to the group of contacts and secondarily adjusted for advancing said terminal to engagement with the contact in the group corresponding to such other telephone line, and means to prevent the connection of a second link circuit of said 10 group with the so-connected telephone line.

122. A telephone exchange system comprising subscribers' lines, automatic switching mechanism adapted to connect with a wanted line, means for associating said mechanism with a calling line, traveling contact terminals for said mechanism, a cut-off relay for the wanted line, a circuit including a contact of said cutoff relay for preventing connection of a second calling 15 line to said wanted line, and an energizing circuit for said cutoff relay including one of said contact terminals.

123. A telephone exchange system comprising subscribers' lines, automatic switching mechanism adapted to connect with a wanted line, a controlling magnet winding for said mechanism, means for associating said mechanism with a calling line, a cut-off relay for the wanted line, traveling contact terminals for said mechanism, a circuit including a contact of said cutoff relay for preventing connection of a second calling line to said wanted line, and an energizing circuit for said cut-off relay including said 20 winding and one of said contact terminals.

124. The combination with a metallic telephone line, of a test terminal therefor, a relay for disconnecting said test terminal from the telephone line when the line is not 25 in use, a connecting circuit and an automatic directly controlled line connecting switch, a source of electricity bridged across said circuit and adapted to send current over the metallic telephone circuit for talking purposes, and means for supplying current to said relay to connect the test terminal when the line is called or is calling and connected, substantially as described.

125. A telephone system including a plurality of telephone lines, a source of calling current, a link circuit provided with connection terminals, an electrically controlled selective mechanism adapted to select and test any desired one of said lines, and means 55 automatically effective responsive to the selection and test of an idle one of said lines for connecting said source through said terminals to said idle line.

126. A telephone system including a plurality of telephone lines, a source of calling current, a link circuit provided with connection terminals, an electrically controlled selective mechanism adapted to associate said link circuit with any desired one of

65 said lines, and means automatically effective responsive to the connection of said link circuit with the talking conductors of an idle one of said lines for connecting said source through said terminals to said idle line.

70 127. In a telephone system, a plurality of telephone lines, a link circuit common to a plurality of lines, a switching device in which said link circuit terminates, electrically controlled means for operating said switching device to connect said link circuit to any one of said lines, automatic test means for determining the busy or idle condition of a wanted line, a source of calling current, and means exclusively under the control of said test means for governing the connection of said source of calling current in circuit with an idle wanted line.

75 128. In a telephone exchange system, a line, another line, means for connecting the two, said means comprising a trunk, a switch associated with one end of said trunk having a terminal of the first line, a switch associated with the other end of the trunk and having a terminal of the second line, a line 80 relay individual to the first line for controlling the operation of the first switch to connect the second switch with the first line before the second switch is operated, a central battery for operating purposes, a busy 85 potential circuit for the trunk, and means for applying a busy potential from said battery for making the trunk busy.

90 129. In an automatic telephone system comprising a plurality of subscribers' telephone lines, individual line-relays, a plurality of automatic switches common to all of said lines, but less in number than the latter, each line being connected with stationary multiple switch-contacts of all of said switches, said contacts being adapted for use in making only out-going calls from said lines, another group of automatic switches common to all of said lines for one subscriber calling another in the group, 95 but less in number than the latter, said lines being also connected with stationary multiple switch-contacts in all of said last mentioned switches, but said last-mentioned contacts being adapted for use in making only 100 incoming calls to said lines.

110 130. An automatic telephone system comprising a plurality of subscribers' telephone lines, individual line-relays, subscribers' switching apparatus adapted for transmitting electrical impulses over the lines, according to the character and number of digits in any called number, and a plurality of automatic switches common to all of said lines, but less in number than the latter, 115 each subscriber's apparatus being adapted for setting up a current-flow sufficient to cause the operation of one of said switches 120 125

preliminary to the transmission of the current-flow to be employed exclusively in calling the number of the called subscriber.

131. An automatic telephone system comprising subscribers' telephone lines, individual line-relays, a group of automatic switches common to all of said lines, but less in number than the latter, each switch having a pair of stationary contacts for each subscriber's line, corresponding contacts of different switches being multiplied together, another set of automatic switches common to all of said lines for one subscriber calling another in the group, but less in number than the latter, these last-named switches being also each provided with a pair of stationary contacts for each line, corresponding contacts of the different last-named switches being multiplied together, and two pairs of "line-normals" for each line, one pair connected to all of the multiple-contacts belonging to such line in one set of switches, and the other pair of "line-normals" connected to all of the multiple-contacts belonging to such line in the other set of switches.

132. In a telephone system, a calling line, an automatic switch associated with said line, means controlled from said line for operating the switch, including a series of contacts, a movable element for said switch associated with said contacts, said operating means all being normally at rest and said element being always movable in the same direction.

133. In a telephone system, a calling line, an automatic switch associated with said line, means controlled from said line for operating the switch to cause it to call the number of the calling line, including a series of contacts, a movable element for said switch associated with said contacts, said operating means all being normally at rest and said element being always movable in the same direction.

134. A telephone system including a pair of connected telephone lines, a pair of selective switches at the exchange through which the talking circuit extends, electromagnetic release means for said switches, respectively, a connection extending between said switches including a wiper contact of one of said switches and separate from the talking circuit connected to said means of both said switches, and means controlled over said talking circuit to simultaneously operate said means to release.

135. In a telephone system, two selecting switches, a trunk line connecting said selecting switches, a pair of controlling relays for one of said selecting switches, disconnecting mechanism for both of said selecting switches, a magnet at each switch for controlling said disconnecting mecha-

nisms, a circuit containing both of said magnets, and a pair of contacts on said controlling relays adapted to control the disconnecting circuit to cause the release of both said selecting switches, substantially as described.

136. In a telephone system, a pair of selecting switches connected by a trunk line, disconnecting devices for each of said selecting switches, a separate conductor extending between said selecting switches for connecting said disconnecting devices, and a pair of controlling relays at one of said selecting switches to close an energizing circuit for said disconnecting devices involving said separate conductor.

137. In a telephone system, a calling line and a called line, a selector switch and a connector switch for extending a talking circuit from the calling line to the called line via a circuit separated into two electrical sections at said connector, a pair of relays bridged across the section nearest the calling subscriber, releasing apparatus for said switches, an energizing circuit for said releasing apparatus, and a pair of contacts controlled jointly by said relays for completing said release circuit.

138. In a telephone system, a pair of automatic switches for extending a line from one point to another, releasing devices in said switches, a release circuit extending between said switches separate from said line, a pair of relays in one of said switches, and a pair of contacts controlled jointly by said relays for energizing said release circuit.

139. A telephone system including a pair of connected telephone lines, a pair of selective switches at the exchange through which the talking circuit extends, electromagnetic release means for said switches, respectively, a circuit extending between said switches including a wiper contact of one of said switches and separate from the talking circuit connected to said means of both said switches, and means for operating said circuit to simultaneously alter the electrical conditions of said means when disconnection is desired.

140. In an automatic telephone system, a pair of selecting switches connected by a trunk line, a separate conductor extending between said selecting switches, disconnecting devices for each of said selecting switches adapted to be included in the circuit of said separate conductor, and a pair of controlling relays at one of said selecting switches adapted to close the circuit through said separate conductor to energize both of said disconnecting devices substantially as described.

141. In a trunk release system, a pair of automatic selector switches, a wiper for one of said switches, a release circuit extending

between said switches including said wiper, a source of current for said release circuit, a release relay coil for one of said switches and a release magnet coil for the other of said switches, both serially included in said release circuit, a release relay for the last named switch, contacts for said relay also in said release circuit for completing the continuity of the same, and means for controlling said last named relay to bring about the release of both said switches.

142. In an automatic trunk release system, a pair of switches, a talking circuit and a release circuit independent thereof temporarily extending between said switches, a source of current, a wiper of one switch, a release relay coil of one switch, a release magnet coil of the other switch, all serially included in said release circuit, a release relay of the latter switch, and contacts thereof also in said release circuit for controlling the release of both switches.

143. In a telephone exchange system, the combination of a line, a connector provided with a pair of line relays, a battery having one pole grounded and the other pole normally connected with both sides of the line through the coils of said relays, and a connector relay for temporarily disconnecting one side of said line and switching it into connection with the grounded pole of the battery, together with a subscriber's telephone receiving talking current from said battery.

144. An automatic telephone system comprising a "selector" provided with four series of contacts, the contacts of two of said series being line-contacts, the third series consisting of "private-contacts", and the fourth series consisting of "release-trunk" contacts, together with a rotatable switch-shaft provided with wipers adapted to engage the contacts of their respective series.

145. An automatic telephone system comprising calling and called subscribers' lines provided with call signalling devices, a central source of talking current, a selector provided with four series of contacts, two of said series being line-contacts, the third series consisting of "private-contacts", and the fourth series consisting of release-trunk-contacts, together with a rotatable switch-shaft provided with wipers adapted to engage their respective series of contacts, means for operating said signalling devices, and means for temporarily disconnecting a called subscriber's line from the central source of talking current during the operation of producing a call-signal at the called subscriber's station.

146. In a telephone system, comprising calling and called subscribers' stations, a line circuit, a battery having one pole grounded and the other pole normally connected with the conductors of said circuit,

means for transmitting ground impulses over one conductor and then the other of said line circuit, suitable devices responsive to said impulses for extending the said circuit in the direction of the called subscriber, means for retaining said battery in its normal relation to the line circuit until the called line is found, and automatic electromagnetically-operated means for then switching the battery in bridge of said circuit.

147. In a telephone system comprising calling and called subscribers' stations, a line circuit, a battery having one pole grounded and the other pole normally connected with the conductors of said circuit, means operated by current from the battery for extending the circuit in the direction of the called subscriber, means operative only after the called line is found for bridging the battery across the line circuit, and a calling subscriber's telephone receiving talking current from said battery after the latter is bridged across the line circuit.

148. In a telephone exchange system, comprising called lines divided into groups, a line, a connector provided with means having motions to select groups and to find the called line in any selected group, provided also with a pair of line relays, a battery having one pole grounded and the other pole normally connected with both sides of the line through the coils of said relays, and a connector relay for temporarily disconnecting one side of said line and switching it into connection with the grounded pole of the battery.

149. In a telephone exchange system, the combination of a line, a battery having one pole grounded and the other pole normally connected with both sides of said line, a connector provided with means having motions to select groups and to find the called line in any selected group, and a relay for temporarily disconnecting one side of the line and switching it into connection with the grounded pole of the battery, together with a subscriber's telephone receiving talking current from said battery, said relay energized during talking.

150. In a telephone system, a calling line, a called line, automatic means for extending a call from a calling to a called line, said means including a line relay, switching means controlled by said relay, a cut-off-relay, and means controlled over the calling line for operating said cut-off-relay, responsive to the calling subscriber, to disconnect by a single movement the line relay before the call reaches the called line.

151. In a telephone system, a trunk-line, a called line, a calling line, automatic means for extending a call from a calling to a called line, said means including a line re-

- lay, switching means controlled by said relay, a cut-off-relay, and means controlled over the trunk-line for operating said cut-off relay, responsive to the calling subscriber, to disconnect by a single movement the line relay before the call reaches the called line.
152. A telephone system comprising a calling line, a called line, automatic means for extending a call from a calling line to a called line, said means including a trunk-line, a bridge including an electromagnetic switch operating element on the trunk-line, a bridge-cut-off relay, and means controlled over the trunk-line for operating said relay, responsive to the calling subscriber, to open by a single movement said bridge before the call reaches the called line.
153. In a telephone system, a calling line, a called line, a line relay, switching means controlled by said relay, a cut-off relay, means controlled over the calling line and from the substation thereof for operating said cut-off relay to disconnect by a single movement the line relay before the call reaches the called line, and a talking circuit controlled by said cut-off relay and closed thereat by the same act which cuts off the line relay.
154. A telephone system comprising a talking circuit, a series of line-switching relays controlling said circuit, and means by which a calling subscriber successively controls said relays in the establishment of said circuit, each relay adapted by a single movement of its armature to close said talking circuit thereat.
155. The combination with a normally open operative circuit, an impulse transmitter arranged therein and a progressively movable mechanism comprising a normally inoperative motor magnet, of a switching relay adapted to render the motor magnet capable of operation when the operating circuit is closed, another switching relay responding to impulses of current transmitted over the operating circuit, said relay being adapted to effect the actuation of the motor magnet in unison with said impulses.
156. A telephone exchange system comprising a conductor; a selecting switch for establishing connection with said conductor, including contacts having primary and secondary movements; a secondary relay for controlling said secondary movement; means including a release magnet for restoring said parts to normal; a release relay for controlling said release magnet; and a circuit for said release magnet including normally open contacts of said release relay and normally open contacts of said secondary relay.
157. An automatic telephone system including selector and connector switches, bank-contacts and co-operating wipers for each of said switches, conductors for said switches normally disconnected from their associated wipers, means for operating said wipers to connect with contacts in their associated banks, and means for thereafter connecting said conductors with said wipers.
158. In a telephone system, a plurality of talking circuits, a selecting switch adapted to hunt for and seize a predetermined circuit, and means for always maintaining said switch in operative relation to one of said circuits whether busy or idle.
159. In a telephone system, subscribers' lines divided into groups, means including automatically progressively movable switches normally disconnected from the subscribers' lines common to said lines and accessible thereto for establishing a talking circuit between a calling and a called subscriber's line, said talking circuit divided into two inductively connected sections, one section on the side of the calling subscriber and another section on the side of the called subscriber, and a battery normally bridged across the calling end of the talking circuit at a point between one of said automatic switches and the called line.
160. In a telephone system, subscribers' lines divided into groups, means including automatic progressively movable switches normally disconnected from the subscribers' lines common to said lines and accessible thereto for establishing a talking circuit between a calling and a called subscriber's line, said talking circuit divided into two inductively connected sections, one section on the side of the calling subscriber and another section on the side of the called subscriber, a battery normally bridged across the calling end of the talking circuit at a point between one of said switches and the called line, and a transmitter for the calling subscriber connected to receive current from said battery.
161. In a telephone system, a called line, a central source of current for talking purposes, means for making the called line busy, means including a progressively movable switch for finding the called line, and means associated with said first means to retain said switch in its operated position for preventing the called line from being signaled.
162. In a telephone system, a called line, a central source of current for talking purposes, means for making the called line busy, means including a progressively movable switch for finding the called line, and means in said switch associated with said first means to retain said switch in its operated position for preventing the called line from being signaled.
163. In a telephone system, a called line, a central source of current for talking purposes, means for making the called line busy,

- means including a progressively movable switch for finding the called line, and means controlled by said first means to retain said switch in its operated position and to prevent a connection from being extended to said called line.
164. In a telephone system, a called line, a central source of current for talking purposes, means for making the called line busy, 10 means including a progressively movable switch, for finding the called line, and means associated with said first means to retain said switch in its operated position for preventing a circuit from being extended from the switch to a station on the called line.
165. In a telephone system, a called line, a central source of current for talking purposes, progressively movable switching mechanism for finding said line, means to retain said switching mechanism in its operated position upon finding said line busy.
166. In a telephone system, a called line, a central source of current for talking purposes, progressively movable switching mechanism for finding said line, and means in said switching mechanism to retain the same in its operated position upon finding said line busy.
167. In a telephone system, a called line, 30 a central source of current for talking purposes, progressively movable switching mechanism for finding said line, means to retain said switching mechanism in its operated position upon finding said line busy, and means for preventing a connection being completed with said called line.
168. In a telephone system, a called line, a central source of current for talking purposes, progressively movable switching 40 mechanism for finding said line, and means to retain said switching mechanism in its operated position upon finding said line busy and for preventing the called line being signaled.
169. In a telephone system, a calling and a called line, a centralized source of current for talking purposes, progressively movable switching mechanism for establishing a connection to the called line, means for making the called line busy, and means for determining the busy condition of the called line and for locking thereon to maintain the connection uncompleted.
170. In a telephone system, a calling and 55 a called line, a centralized source of current for talking purposes, progressively movable switching mechanism for establishing a connection to the called line, means for making the called line busy, and means in said switching mechanism for determining the busy condition of the called line and for locking thereon to maintain the connection uncompleted.
171. In a telephone system, a calling and 60 a called line, progressively movable switch-
- ing mechanism for establishing a connection to the called line, means for making the called line busy, means for determining the busy condition of the called line and for locking thereon to maintain the connection 70 uncompleted, and means brought into operation after the busy called line is found for transmitting a signal to the calling line.
172. In a telephone exchange system, the 75 combination of a telephone line, a bridge on said line, a bridge cut-off relay, automatic means for energizing said relay when the line calls, controlled by the calling subscriber, and automatic means for energizing 80 the relay when the line is called.
173. In a telephone exchange system, the combination of a telephone line, a line relay to be cut off from the line, a cut-off relay, a circuit for energizing said cut-off relay, 85 automatic means for closing said circuit when the line calls, controlled by the calling subscriber, another circuit for energizing the cut-off relay when the line is called.
174. In a telephone exchange system, the 90 combination of a telephone line, a line relay to be cut off from the telephone line, a trunk line, automatic means for connecting the telephone line with the trunk line, a cut-off 95 relay, means for energizing the cut-off relay simultaneously with the establishment of connection with the trunk line, and means for energizing the cut-off relay when the telephone line is called.
175. In a telephone exchange system, the 100 combination of a telephone line, a normally disconnected terminal for said line, a line relay to be cut off from the line, a cut-off 105 relay, means for connecting the terminal with the line when the cut-off relay is energized, means for disconnecting the line relay when the cut-off relay is energized, automatic means for energizing the cut-off relay when the line calls, controlled by the calling subscriber, and means for energizing 110 the cut-off relay when the line is called.
176. In a telephone exchange system, the combination of a telephone line, a normally disconnected terminal for said line, a line relay to be cut off from the line, a cut-off 115 relay, means for connecting the terminal with the line when the cut-off relay is energized, means for disconnecting the line relay when the cut-off relay is energized, automatic means for energizing the cut-off relay when the line calls, controlled by the calling subscriber, and means for energizing 120 the cut-off relay when the line is called, together with means by which a calling subscriber controls said last mentioned energizing means.
177. A telephone system comprising a talking circuit, automatic means for extending a call from a calling to a called line said means including a line relay, switching 125
- 130

means controlled by said relay, a cut-off relay adapted and operative by a single movement of its armature to cut off the line relay and close the talking circuit thereat before the call reaches the line of the called subscriber, and means by which the calling subscriber controls said cut-off relay.

178. A telephone exchange system comprising subscribers' telephone lines, inter-
10 connecting link circuits, line selectors, and electrically directly controlled switches for cooperating with said line selectors to unite said lines into conversational circuits, manual impulse transmitting means at the substations for controlling said directly controlled switches, and means whereby the act of establishing such a conversational circuit will operate only those switches whose contacts are included in the finally completed talking circuit.

In witness whereof, I, hereunto subscribe 20 my name this ninth day of November A. D., 1903.

FRANK R. McBERTY.

Witnesses:

GEORGE P. BARTON,
W. W. LEACH.
